TELEPHONE SYSTEM

Thomas Frederick Crocker, Chicago, Ill., assignor
to Associated Electric Laboratories, Inc., Chi-
cago, Ill., a corporation of Delaware

Application December 29, 1939, Serial No. 311,552

38 Claims. (CL. 179—27)

The present invention relates to telephone systems and more particularly to improved arrangements for distributing calls in telephone systems of the semi-automatic type.

In a conventional telephone system of the semi-automatic type the various manual telephone lines terminate in jacks at the A and B operator positions; and an automatic switch train provided with a distributing system is interposed between the A operator positions and the B operator positions. In a telephone system of this type, calls on the telephone lines are answered directly by the operators at the A operator positions and routed by the switch train under the control of the distributing system to the B operator positions to be completed.

Accordingly in telephone systems of this type, the traffic between the A operator positions and the B operator positions is governed by the distributing system. However, the traffic between the calling telephone lines and the various A operator positions is not governed but remains under the manual control of the operators at the A operator positions, rendering the number of calls on the telephone lines answered by an operator at a given A operator position and routed therefrom to the B operator positions to be completed entirely within the discretion of the operator at the given A operator position.

Accordingly, it is an object of the present invention to provide in a telephone system of the type described, improved apparatus for distributing calls on telephone lines to a number of A operator positions to be answered.

Another object of the invention is to provide in a telephone system including a number of A operator positions and a number of B operator positions, an improved arrangement for distributing and for storing incoming calls on telephone lines to the A operator positions to be answered and recalls on established connections from the B operator positions to the A operator positions to be answered.

Another object of the invention is to provide in a telephone system including a number of operator positions, an improved arrangement for distributing and for storing incoming calls on telephone lines to the operator positions to be answered.

Another object of the invention is to provide in a telephone system including a number of operator positions provided with facilities for establishing connections between telephone lines, an improved arrangement for distributing and

storing recalls on the established connections to the operator positions to be answered.

A further object of the invention is to provide in a telephone system including an operator position, improved switching apparatus for routing a call to the operator position to be answered and for extending the call from the operator position after it has been answered.

A further object of the invention is to provide in a telephone system including an operator position, an improved switching link for establishing a connection between a calling line and a called line, which switching link is under the joint control of automatic apparatus and an operator at the operator position.

A further object of the invention is to provide in a telephone system including an operator position, an improved switching link selectively operative to establish a connection between a calling line and a called line including the operator position and to establish a direct connection between the calling line and the called line excluding the operator position, and apparatus under the control of an operator at the operator position for selectively controlling the operation of the switching link.

A further object of the invention is to provide in a telephone system including an operator position, improved apparatus at the operator position for supervising calling telephone lines in the system and established connections between telephone lines in the system and for performing service functions over the telephone lines in the system.

The features of the present invention are illustrated as being incorporated in a telephone system comprising an exchange terminating a plurality of manual telephone lines and including a number of A operator positions, a number of B operator positions and a number of switching links. The switching links have access to the telephone lines, to the A operator positions and to the B operator positions; while the B operator positions have access to the telephone lines. The telephone lines comprise three classes which are rendered corresponding classes of service consisting of flat rate service, call register service and prepay service.

In accordance with one feature of the invention, the telephone system comprises a plurality of subscriber lines, a plurality of A operator positions, a B operator position, a plurality of storage units individually associated with the A operator positions, and means for assigning the storage units in a predetermined order. Also, the sys-

tem comprises means for routing a call on any one of the subscriber lines to an idle one of the A operator positions to be answered when one of the A operator positions is idle, means for routing a call upon the one subscriber line to an assigned one of the storage units to be stored when all of the A operator positions are busy, and means for routing a call upon the one subscriber line stored in the assigned storage unit to the associated one of the A operator positions to be answered when the associated A operator position becomes idle. Also, the system comprises means for routing a call upon the one A operator position to the B operator position and means for establishing a connection between the one subscriber line and the B operator position independent of the one A operator position, thereby to route a call from the one subscriber line to the B operator position. Further, the system comprises means for routing a recall by an operator at the B operator position upon the established connection to an idle one of the A operator positions to be answered when one of the A operator positions is idle, means for routing a recall upon the established connection to an assigned one of the storage units to be stored when all of the A operator positions are busy, and means for routing a recall upon the established connection stored in the assigned storage unit to the associated one of the A operator positions to be answered when the associated A operator position becomes idle.

In accordance with another feature of the invention, the arrangement for routing the calls and recalls from and to the A operator positions, the B operator position and the storage unit comprises switching apparatus including a plurality of switching links, wherein each switching link includes a first branch provided with an answer switch having access to calling lines and a second branch provided with a call switch having access to called lines. Also, a link distributor is provided for assigning idle ones of the switching links for use in a predetermined order and for causing the finder switch of an assigned link to seize a calling line; while a position distributor is provided for assigning idle ones of the operator positions for use in a predetermined order and for assigning the storage units for use in a predetermined order when all of the operator positions are busy. Further, the system comprises calling means under the control of an operator at any one of the operator positions to which the call on a link is routed for governing the operation of the call switch of the link, thereby to extend the call from the one operator position, means at the one operator position for completing a three-way communication connection including the telephone apparatus at the one operator position and the first and the second branches of the link, and means under the control of an operator at any one of the operator positions for completing a communication connection between the first and the second branches of the link independent of the one operator position. Also, the system comprises means under the joint control of any one of the calling lines and an operator at any one of the operator positions to which a call on the corresponding one of the links is routed for releasing the connection prior to operation of the calling means, and means under the joint control of any one of the calling lines and the corresponding one of the called lines for releasing the connection subsequent to the operation of the transfer means.

In accordance with another feature of the in-

vention, the system comprises, in addition to the storage units individually associated with the operator positions, a plurality of conservators individually associated with the storage units,

- 5 wherein each of the storage units has a limited storage capacity and each of the conservators has an unlimited conservation capacity. The position distributor is operative to assign the storage units in a predetermined order when all of the
- 10 operator positions are busy and to assign the conservators in a predetermined order when the storage capacities of the storage units are exhausted. The switching apparatus is operative to route the calls on the links to the operator positions to be answered when the operator positions are idle, to route the calls on the links to assigned ones of the storage units to be stored, to route the calls on the links stored in the assigned storage units to the associated ones of the
- 15 operator positions to be answered when the associated operator positions become idle, to route the calls on the links to assigned ones of the conservators to be conserved, and to route the calls on the links conserved in the assigned conservators to the associated ones of the storage units to be stored when the storage capacities of the associated storage units are replenished. Further, the switching apparatus is operative to route the calls on the links stored in the assigned
- 20 storage units to the associated ones of the operator positions to be answered and to route the calls on the links conserved in the assigned conservators to the associated ones of the storage units to be stored independently of the position distributor.

In accordance with a further feature of the invention, the switching apparatus comprises a plurality of relays, the relays being arranged in a plurality of first groups individually associated with the operator positions and in a plurality of second groups individually associated with the links, whereby each relay is included in a particular first group and in a particular second group and is operative to connect the associated link to the associated operator position. The position distributor is operative to prepare the first groups of relays in a predetermined order; and means is provided which is controlled by the presence of a call on an assigned one of the links for causing operation of the associated one of the relays in a prepared first group of relays, thereby to extend the call on the assigned link to the operator position associated with the one relay to be answered, the one relay being included in a given first group and in a given second group. Also, the switching apparatus comprises means controlled by the operation of the one relay for preventing operation of the other relays in the given first group and the other relays in the given second group.

In accordance with a further feature of the invention, the system comprises a plurality of groups of links, a plurality of groups of feeder trunks individually associated with the groups of links, a plurality of groups of automatic switches individually associated with the groups of links, a plurality of operator positions, and a plurality of position trunks individually associated with the operator positions, each of the position trunks being associated with corresponding feeder trunks in the groups of feeder trunks. Also, the system includes a position distributor for selecting corresponding feeder trunks in the groups of feeder trunks and corresponding switches in the groups of switches in a predetermined order, means

controlled by the presence of a call on any one of the links in any one of the groups of links for connecting the one link in the one group of links to the selected feeder trunk in the associated one of the groups of feeder trunks and for preventing the other links in the one group of links from being connected to the selected feeder trunk in the one group of feeder trunks and for operating the selected switch in the associated one of the groups of switches. Further, the system comprises means controlled by the operation of the selected switch in the one group of switches for connecting the selected feeder trunk in the one group of feeder trunks to the associated one of the position trunks and for preventing the corresponding feeder trunks in the other groups of feeder trunks from being connected to the one position trunk, thereby to extend the call on the one link in the one group of links to the operator position associated with the one position trunk to be answered.

In accordance with a further feature of the invention, the system comprises a plurality of telephone lines of different classes; a plurality of line circuits of corresponding classes individually associated with the telephone lines, the line circuits of different classes having different impedance characteristics; means for testing the impedance characteristic of the line circuit associated with a telephone line included in an established connection extending between the telephone line and the operator position; a plurality of signals associated with the operator position and corresponding to the different classes of telephone lines; and means controlled by the testing means for selectively controlling the operation of the signals, whereby a signal corresponding to a particular class of telephone lines is operated when a connection is completed between any telephone line of the particular class and the operator position.

In accordance with a further feature of the invention, the system includes a group of two-party subscriber lines, each of these lines having a line circuit associated therewith which includes first and second registers and a lockout relay, an operating circuit and a holding circuit being provided for the lockout relay. Means is provided at the operator position to which a call is routed from one of the subscriber lines for selectively operating the first and second registers; and means is provided at the operator position for completing the operating circuit of the lockout relay in the line circuit associated with the two-party subscriber line, thereby to cause the lockout relay to operate and complete the holding circuit therefor in the event there is a calling condition on the associated subscriber line. Further, the system comprises means controlled by the operation of the lockout relay for causing restoration of the switching apparatus over which the call from the line to the operator position is routed, additional means controlled by the operation of the lockout relay for preventing reoperation of the switching apparatus, and means controlled when the calling condition is removed from the subscriber line for interrupting the holding circuit for the lockout relay, thereby to cause the lockout relay to restore.

Further features of the invention pertain to the particular arrangement of the circuit elements thereof, whereby the above-outlined and additional operating features are attained.

The novel features believed to be characteristic of the invention, both as to its organization

and method of operation, together with further objects and advantages thereof, will best be understood by reference to the following specification taken in connection with the accompanying

5 drawings in which Figure 1 illustrates the general arrangement of a telephone system including a local exchange and a distant exchange embodying the present invention; and Figs. 2 to 8, inclusive, taken together, illustrate the details of a
10 system having incorporated therein the features of the invention, as briefly outlined above.

Description of the apparatus incorporated in the telephone system

15 Referring now more particularly to Fig. 1 of the drawings the telephone system there illustrated comprises a local exchange 20, a distant exchange 30 and a plurality of one-way trunk lines, including the trunk line 670, extending therebetween. 20 The local exchange 20 and the distant exchange

20 The local exchange 20 and the distant exchange 30 are of the manual type, each serving a num-

ber of groups of telephone stations to which different classes of service are rendered. For example, the local exchange 20 serves a group of subscriber substations, including the subscriber substation T1, which is rendered flat rate service; a group of party subscriber substations, including the party subscriber substations T2 and T3, which is rendered call register service; and

30 a group of paystations, including the paystation T4, which is rendered prepay service. A telephone line having a line circuit individually associated therewith extends to each telephone station in the local exchange; the telephone lines

35 225, 270 and 285 respectively extending to the subscriber substation T1, the party subscriber substations T2 and T3, and the paystation T4.

The flat rate line circuit 200 is individually associated with the telephone line 225; the two-party line register circuit 240 is individually associated with the telephone line 210; and the prepay manual line circuit 280 is individually associated with the telephone line 285. Each of the subscriber substations and paystations in the local exchange 20 is provided with station equipment, including a telephone instrument and a ringer.

Also, the local exchange 20 comprises a number of A operator positions, including the first

50 A operator position 700, the second A operator position 505 and the last A operator position L505; a number of B operator positions, including the first B operator position 694; and a number of tall operator positions, including the

55 number of toll operator positions, including the toll operator position 699. Each A operator position has a position number individually and

sition has a position trunk individually extending thereto, the position trunks 470, 570 and L570 individually extending to the A operator position 150, 540 and L530.

60 tions 700, 505 and L505, respectively; each B operator position has a group of trunks individually extending thereto, the trunk 698 being included in the group of trunks individually extending to the first B operator position 694; and

65 tending to the first B operator position 694, and each toll operator position has a group of trunks individually extending thereto, the trunk 695 being included in the group of trunks individ-

being included in the group of trunks individually extending to the toll operator position 699. Each trunk extending to each B operator position is provided with a trunk line indicator.

70 tation is provided with a trunk line circuit individual thereto, the trunk line circuit 680 being individual to the trunk 680 extending to the first B operator position 694; and each trunk extending to each toll operator position is provided with a trunk line circuit individual thereto, the 75 trunk line circuit 697 being individual to the

trunk 695 extending to the toll operator position 699. Also, each trunk line extending between the local exchange 20 and the distant exchange 30 is provided with a trunk line circuit individual thereto, the trunk line circuit 672 being individual to the trunk line 670 extending between the local exchange 20 and the distant exchange 30.

Further, the local exchange 20 comprises a number of groups of finder-selector links comprising the first group of links, including the links 100, 101 and 102, and the second group of links, including the links 103, 104 and 105; and a number of link distributors individually associated with the groups of links, including the link distributors 301 and 112 individually associated with the first and second groups of links, respectively. The link distributor 301 is operative to assign idle ones of the links in the first group of links in a predetermined order to the use of the lines in a first group of telephone lines; while the link distributor 112 is operative to assign idle ones of the links in the second group of links in a predetermined order to the use of the telephone lines in a second group of telephone lines, the telephone lines being divided into groups individually associated with the groups of links. Each link comprises a finder switch and a selector switch. For example, the first link 100 in the first group of links comprises a finder switch 300 and a selector switch 600; while the first link 103 in the second group of links comprises a finder switch 123 and a selector switch 133.

Further, the local exchange 20 comprises switching apparatus associated with the links in the various groups of links and including a plurality of groups of feeder trunks individually associated with the groups of links. The first group of feeder trunks, including the feeder trunks 480 and 580, is individually associated with the first group of links; and the group of feeder trunks, including the feeder trunks 140 and 141, is individually associated with the second group of links. Further, it is noted that corresponding feeder trunks in the groups of feeder trunks are commonly associated with the position trunks extending to the A operator positions. For example, the first feeder trunk 480 in the first group of feeder trunks and the first feeder trunk 140 in the second group of feeder trunks are commonly associated with the position trunk 470 extending to the first A operator position 700; while the second feeder trunk 580 in the first group of feeder trunks and the second feeder trunk 141 in the second group of feeder trunks are commonly associated with the position trunk 570 extending to the second A operator position 505. Further, the switching apparatus comprises a plurality of groups of sequence switches individually associated with the groups of links, the first group of sequence switches, including the sequence switches 410 and 510, being individually associated with the first group of links; and the second group of sequence switches, including the sequence switches 110 and 111, being individually associated with the second group of links. Finally, the switching apparatus comprises a plurality of groups of switching units individually associated with the position trunks, the first switching unit 400 and the second switching unit 150 in the first group of switching units being commonly associated with the position trunk 470 extending to the first A operator position 700; and

the first switching unit 500 and the second switching unit 151 in the second group of switching units being commonly associated with the position trunk 570 extending to the second A operator position 505.

Further, the local exchange 20 comprises a plurality of storage units individually associated with the A operator positions, the first and second storage units 800 and 810 being respectively associated with the first and second A operator positions 700 and 505. Each storage unit has a marking trunk extending thereto, the marking trunks 870 and 895 respectively extending to the first storage unit 800 and the second storage unit 810. Also, a plurality of control trunks are individually associated with the operator positions, the control trunks 490 and 590 being respectively associated with the first A operator position 700 and the second A operator position 505. Finally, the local exchange 20 comprises an A operator position distributor 830 for assigning in a predetermined order idle ones of the A operator positions to receive calls and for assigning the storage units in a predetermined order when all of the A operator positions are busy. Also, a distributor trunk 880 extends from the A operator position distributor 830 to each switching unit in each group of switching units.

Each of the finder switches, such, for example, as the finder switch 300, constitutes an answer switch having access to each telephone line in the associated group of telephone lines in the local exchange; while each of the selector switches, such, for example, as the selector switch 600, constitutes a call switch having access to each of the trunks extending to the B operator positions and the toll operator positions and to each of the trunk lines extending to the distant exchange 30. Each sequence switch in each group of sequence switches has access to the control trunk extending to the associated A operator position and to the storage unit associated with the associated A operator position. Also, it is noted that each B operator position in the local exchange 20 has access to each telephone line therein.

The distant exchange 30 comprises a number of A operator positions, not shown, and a number of B operator positions, including the B operator position 698. It is noted that the trunk line 670 extending between the local exchange 20 and the distant exchange 30 is terminated at the B operator position 698 in the distant exchange 30.

Preferably, each of the finder-selector links is identical to the first link 100 in the first group of links illustrated which comprises a finder switch 300 and a selector switch 600, as previously noted. The finder switch 300, as best shown in Fig. 3, comprises a switching mechanism 310 of the 200-point Strowger type including a carriage provided with a first wiper set, including the wipers 311, 312 and 313, a second wiper set, including the wipers 314, 315, 316 and 317, and a control wiper 318. It is noted that the wipers 311, 312 and 313 of the first wiper set and the wipers 314, 315, 316 and 317 of the second wiper set are capable of both vertical and rotary movements; while the control wiper 318 is capable of vertical movement. Further the mechanism 310 comprises a circumferentially disposed main contact bank provided with two sections respectively associated with the first and second wiper sets and a vertical control contact bank associated with the control wiper 318. Ac-

cordingly, in the mechanism 310, the first and second wiper sets respectively have access to first and second groups of one hundred lines each, respectively terminated by the first and second sections of the main contact bank. Also, the mechanism 310 is provided with a vertical magnet M365 for moving the first and second wiper sets thereof in the vertical direction, a rotary magnet M367 for moving the first and second wiper sets thereof in the rotary direction and a release magnet M369 for releasing the first and second wiper sets thereof and for causing these wiper sets to be returned to their normal positions. Finally the mechanism 310 has three sets of switch springs S370, S371 and S372 operatively associated therewith which are controlled in accordance with the movements of the first and second wiper sets thereof, in a manner more fully described subsequently.

Also, the finder switch 300 comprises a number of relays, including two switching relays R320 and R330 and a start relay R340 connected and arranged in a manner more fully described subsequently.

The selector switch 600, as best shown in Fig. 6, comprises a switching mechanism 610 of the 100-point Strowger type including a carriage provided with a wiper set including the wipers 611, 612 and 613. It is noted that the wipers 611, 612 and 613 of the wiper set are capable of both vertical and rotary movements. Further the mechanism 610 comprises a circumferentially disposed main contact bank associated with the wiper set. Accordingly, the wiper set has access to a group of one hundred lines terminated by the main contact bank. Also the mechanism 610 is provided with a vertical magnet M614 for moving the wiper set thereof in the vertical direction, a rotary magnet M616 for moving the wiper set thereof in the rotary direction and a release magnet M618 for releasing the wiper set thereof and for causing the wiper set to be returned to its normal position. Finally the mechanism 610 has a number of switch springs S619, S620, S621 and S622 operatively associated therewith which are controlled in accordance with the movements of the wiper set thereof in a manner more fully described subsequently.

Also the selector switch 600 comprises a number of relays including a lockout relay R625, a battery supply relay R630, a control relay R640, a call back relay R645, an error relay R650, a line relay R655, a hold relay R660, a transfer relay R665 and a switching relay R670 connected and arranged in a manner more fully described subsequently.

Preferably, each of the switching units is identical to the first switching unit 400 in the first group of switching units, which comprises, as partially shown in Fig. 4, the first sequence switch 410 in the first group of sequence switches, a start relay R430, a stop relay R440, a number of feeder relays individually associated with the links in the first group of links and commonly associated with the first feeder trunk 480 in the first group of feeder trunks, including the feeder relay R450 individually associated with the first link 100 in the first group of links and the first feeder trunk 480 in the first group of feeder trunks, and a position relay R460 commonly associated with the first feeder trunk 480 in the first group of feeder trunks and the position trunk 470 extending to the first A operator position 700. The sequence switch 410 is of the rotary type and comprises four wipers 411, 413, 415 and 417 provided with individually associated rotary contact banks 412, 414, 416 and 418. Also, the sequence switch 410 is provided with a rotary magnet M419 for moving the wipers noted in the rotary direction.

The first link distributor 301, illustrated in Fig. 3, has access to each of the links in the first group of links in the local exchange 20 and is operative to assign an idle one of the links in the first group of links to the use of any one of the telephone lines in the first group of telephone lines in the local exchange 20. The details of the connection and arrangement of the link distributor 301 are not disclosed as they form no part of the present invention; however, for reference purpose, it is noted that the connection and arrangement of a distributor of the type of the distributor 301 is shown in the copending application of Edward S. Peterson, Serial No. 233,021, filed October 3, 1938. Also, a marking network 305, shown in Fig. 3, is individually associated with the distributor 301 in order to initiate operation thereof when a call is initiated on any one of the telephone lines in the first group of telephone lines in the local exchange.

Preferably, each of the flat rate line circuits is identical to the flat rate line circuit 200 individually associated with the telephone line 225 extending to the subscriber substation T1, shown in Fig. 2, which comprises a line and cutoff relay R210 and a busy relay R220 connected and arranged in a manner more fully described subsequently. Further it is noted that a tone transformer 246 is commonly associated with each of the flat rate line circuits.

Preferably, each of the two-party line register circuits is identical to the two-party line register circuit 240 individually associated with the telephone line 210 extending to the party subscriber substations T2 and T3, shown in Fig. 2, which comprises a line and cutoff relay R260, a lockout relay R250, a control relay R245 and two registers respectively provided with register magnets M241 and M242, and connected and arranged in a manner more fully described subsequently. Also a signal lamp L243 is individually associated with the two-party line register circuit 240.

Preferably each of the prepay manual line circuits is identical to the prepay manual line circuit 280 individually associated with the telephone line 285 extending to the pay station T4, shown in Fig. 2. The prepay manual line circuit 280 comprises a line circuit of any known connection and arrangement; the details of the connection and arrangement of the line circuit 280 are not disclosed as they form no part of the present invention.

Preferably each of the trunk line circuits is identical to the trunk line circuit 680 individually associated with the trunk 690 extending to the first B operator position 694, shown in Fig. 6, which comprises a line relay R680 and a busy relay R685 connected and arranged in a manner more fully described subsequently.

Preferably each of the B operator positions in the local exchange 20 is identical to the first B operator position 694, shown in Figs. 6 and 2. The first B operator position 694 comprises conventional answering equipment, not shown; conventional calling equipment including a number of call jacks J201, J202 and J203 respectively terminating the telephone lines 225, 270 and 285; and a number of conventional cord circuits, not shown.

Preferably each of the A operator positions is identical to the first A operator position 700, shown in Figs. 7 and 8, which comprises a trunk circuit provided with a set of position keys including an error release key K750, a permanent lockout release key K755, a reverting call key K770, a split key K775, a coin collect key K780, a coin return key K785, a first register key K795, a second register key K790, a transfer key K765 and a control key K760. Also the trunk circuit at the first A operator position 700 comprises a telephone instrument including a transmitter 708 and a receiver 701, a repeater 701, an impedance element I758, a key sender K720 and a number of relays including three tone relays R715, R720 and R725, a rear split relay R730, a front split relay R735, an impulse relay R740, two signal relays R885 and R890, a control relay R710 and a start relay R770. Also associated with the first A operator position 700 are a peg count meter provided with a register magnet M747 and three signal lamps including a flat rate signal lamp L680, a message register signal lamp L881 and a prepay signal lamp L882. The key sender K720 is of a well-known type; accordingly, the details of the connection and arrangement thereof are not disclosed as they form no part of the present invention.

Preferably, each of the call storage units is identical to the call storage unit 800 individually associated with the first A operator position 700, which comprises, as shown in Fig. 8, six marking relays 1M to 6M, inclusive, a control relay R810 and a release relay R820 connected and arranged in a manner more fully described subsequently. Also, six storage lamps L801 to L806, inclusive, are associated with the call storage unit 800 and individually associated with the first A operator position 700.

The A operator position distributor 830, shown in Fig. 8, comprises a number of position relays R850, R860, R870, etc., respectively corresponding to the A operator positions, a control relay R835 and a busy relay R830 connected and arranged in a manner more fully described subsequently.

A better understanding of the connection and arrangement of the apparatus incorporated in the telephone system will be facilitated from a consideration of the detailed operation of the various pieces of apparatus incorporated therein incident to the completion and the handling of the various calls at the first A operator position 700, as will appear hereinafter.

General operation of the system

Considering now the general operation of the system, with reference to Fig. 1 of the drawings it is noted that when a call is initiated at any one of the subscriber substations or at any one of the pay stations in the local exchange 20, the line circuit individually associated with the telephone line extending thereto is controlled, thereby to initiate operation of the link distributor associated with the group of telephone lines including the calling telephone line. Assuming that the calling telephone line is included in the first group of telephone lines, operation of the first link distributor 301 is initiated. The distributor 301 is of the preselective type and operates to select an idle one of the links in the first group of links when a previously selected link in the first group of links is assigned to the use of a calling telephone line. Accordingly, at this time, the distributor 301 operates in order

to assign a previously selected one of the links in the first group of links, such, for example, as the first link 400 in the first group of links, to the use of the calling telephone line in the first group of telephone lines, whereupon the finder switch 300 thereof operates to seize the calling telephone line, at which time operation of the first switching unit in one of the groups of switching units associated with the first group of links is initiated. When the finder switch 300 seizes the calling telephone line in the first group of telephone lines the distributor 301 is released and operates to preselect another idle link in the first group of links as previously noted.

The A operator position distributor 830 pre-selects an idle one of the A operator positions for use, and when a preselected one of the A operator positions is taken for use the A operator position distributor 830 operates to pre-select another one of the A operator positions for use. Assuming that the A operator position distributor 830 has preselected the first A operator position 700 for use at this time, operation of the first switching unit 400 in the first group of switching units is initiated. More particularly, the first switching unit 400 in the first group of switching units operates to connect the first link 400 in the first group of links to the first feeder trunk 480 in the associated group of feeder trunks, to prevent any of the other links in the first group of links from being connected to the first feeder trunk 480, to initiate operation of the first sequence switch 410 in the first group of sequence switches and to cause the A operator position distributor 830 to preselect another A operator position at this time. The first sequence switch 410 then operates to cause the first switching unit 400 to operate further and connect the feeder trunk 480 to the position trunk 470, thereby to extend the call from the calling telephone line in the first group of telephone lines to the first A operator position 700, and to prevent any of the other feeder trunks in the other groups of feeder trunks from being connected to the position trunk 470. The operator at the first A operator position 700 answers the call and operates the key sender at her position, thereby to control the operation of the selector switch 600 in order to extend the call to its destination.

In this connection it is noted that the selector switch 600 may be selectively controlled to extend the call to any idle B operator position in the local exchange 20, to any idle toll operator position in the local exchange 20, or to the B operator position 698 in the distant exchange 30. In the event the call is to be routed to a telephone station in the local exchange 20 the selector switch 600 is controlled in order to route the call to an idle B operator position in the local exchange 20. The operator at the idle B operator position in the local exchange 20 answers the call and then extends the call to the called telephone station in the local exchange 20, in the usual manner. In the event the call is to be routed to a telephone station in the distant exchange 30 the selector switch 600 is controlled in order to route the call to the B operator position 698 in the distant exchange 30. The operator at the B operator position 698 in the distant exchange 30 answers the call and then extends the call to the called telephone station in the distant exchange 30, in the usual manner. In the event the call is to be routed toll the selector switch

600 is controlled in order to route the call to an idle one of the toll operator positions in the local exchange 20. The operator at the idle toll operator position in the local exchange 20 answers the call and then routes the call toll in the usual manner.

After the call has been routed from the first A operator position 700 in the local exchange 20 to an idle one of the B operator positions in the local exchange 29, to an idle one of the toll operator positions in the local exchange 20, or to the B operator position 698 in the distant exchange 30 and the information concerning the extension of the call has been conveyed to the called operator, the operator at the first A operator position 700 releases the connection between her position and the first link 100, whereupon a direct connection is completed between the finder switch 309 and the selector switch 600 excluding the first A operator position 700.

It is noted that the called operator to which the call is routed by the selector switch 600 may recall the operator at an idle one of the A operator positions in the local exchange 20 by causing reoperation of the first switching unit in one of the groups of switching units under the control of the A operator position distributor 830 in the manner previously explained.

In the event all of the A operator positions in the local exchange 20 are busy when operation of the first switching unit in one of the groups of switching units is initiated, the particular operating first switching unit, as determined by the A operator position distributor 830, operates to cause the call or recall on the first link to be stored in an assigned one of the storage units. More particularly, when all of the A operator positions are busy, the A operator position distributor 830 operates to assign the storage units in a predetermined order. Assuming that the A operator position distributor 830 has operated to assign the first call storage unit 800 individually associated with the first A operator position 700 at this time, due to the busy condition of all of the A operator positions, when operation of the first switching unit 400 is initiated, the operating first switching unit 400 reconnects the first link 100 to the feeder trunk 480 and initiates operation of the first sequence switch 410, whereupon the first selector switch 410 seizes the first call storage unit 800, thereby to cause the call or recall on the first link 100 to be stored in the first call storage unit 800 at this time. At this time, when all of the A operator positions are busy, the calls and recalls on the links are stored in the successive storage positions of the storage units in a predetermined order.

At this time, when a number of calls and recalls on a number of the links are stored in one of the call storage units, such, for example, as the first call storage unit 800, further operation of the first call storage unit 800 is initiated when the associated first A operator position 700 becomes idle. More particularly, when the first A operator position 700 becomes idle, the first call storage unit 800 operates, thereby to cause reoperation of the switching unit in the first group of switching units associated with the link having a call or recall thereon stored in the first storage position of the first call storage unit 800, thereby to cause the call or recall on the last-mentioned link to be routed to the first A operator position 700 to be answered. Further, the first call storage unit 800 causes reoperation of each of the switching units in the first group

of switching units associated with the links having calls or recalls thereon stored in the other storage positions of the first call storage unit 800, thereby to cause the calls or recalls on the last-mentioned links to be restored in successive advanced storage positions in the first call storage unit 800. Accordingly, the first call storage unit 800 operates to cause calls and recalls routed thereto to be stored in a predetermined order 10 when all of the A operator positions in the local exchange 20 are busy; and to cause the stored calls and recalls to be released to be answered at the first A operator position 700 in the same predetermined order in which they were stored in 15 the first call storage unit 800.

After a call from a calling telephone line in any one of the groups of telephone lines has been extended from any one of the A operator positions to one of the B operator positions in 20 either the local exchange 20 or the distant exchange 30 or to one of the toll operator positions in the local exchange 20 the release of the established connection is under the joint control of the calling telephone line and the called one of 25 the operator positions.

Flat rate subscriber substation call

A call from a flat rate subscriber substation, such, for example, as the subscriber substation T1, is initiated by removing the receiver of the telephone instrument thereat from its switchhook. When the receiver of the telephone instrument at the subscriber substation T1 is removed from its switchhook, a bridge path is completed between the line conductors C226 and C227 of the telephone line 225 extending to the subscriber substation T1. When this bridge path is completed between the line conductors of the telephone line 225 a circuit is completed for energizing in series the windings of the line and cutoff relay R210. This circuit extends from ground by way of the lower winding of R210, the contacts 212, C227, the bridge path between the line conductors C227 and C226, C226, the contacts 211 and the upper and intermediate windings of R210 to battery. When energized over the above-traced circuit the line and cut-off relay R210 operates partially, thereby to complete, at the contacts 214, a path for applying ground potential to the start conductor C230 and to complete, at the contacts 213, an obvious connection between the control conductors C228 and C229 of the telephone line 225. The path for applying ground potential to the start conductor C230 extends from ground by way of the contacts 221, 215 and 214 to the start conductor C230. The application of ground potential to the start conductor C230 completes an obvious path for applying ground potential by way of the resistor 304 of the marking network 305 to the start conductor C308 extending to the distributor 301, and completes an obvious path for applying direct ground potential to the first contacts in the vertical control contact banks of the finder switches. The application of ground potential to the start conductor C308 initiates operation of the distributor 301 and the application of direct ground potential to the first contacts in the vertical control contact banks of the finder switches marks the telephone line 225 as terminating in the first level of the main contact banks of the finder switches having access thereto.

The distributor 301 is of the preselective type and operates to select another idle link in the first group of links as soon as the finder switch

of a previously selected link in the first group of links operates to find a calling telephone line after it has been taken for use. Assuming that the distributor 301 has previously selected the link 100 illustrated in the first group of links to be taken for use at this time, the distributor 301 operates to cause ground potential to be applied to the start conductor C302, thereby to complete an obvious circuit for energizing the winding of the start relay R340. The start relay R340 then operates to interrupt, at the contacts 348, a point in a multiple path for applying ground potential to the all-link-busy conductor C309 and to complete, at the contacts 342, an obvious path for applying ground potential to the control conductor C363 of the trunk 360. The previously mentioned path for applying ground potential to the all-link-busy conductor C309 in the finder switch 300 extends, when completed, from ground by way of the contacts 348 and the set of switch springs S312 to the all-link-busy conductor C309. Also, the start relay R340 completes, at the contacts 343, obvious multiple circuits for energizing the lower windings of the switching relays R320 and R330, thereby to render each of these switching relays extremely fast to operate in the event the upper winding thereof is energized. Further the start relay R340 prepares, at the contacts 347, a circuit traced hereinafter for energizing the vertical magnet M365 and prepares, at the contacts 346, a circuit traced hereinafter for energizing the rotary magnet M367.

The distributor 301 then operates to cause ground potential to be applied to the vertical conductor C305, thereby to complete the previously mentioned circuit for energizing the vertical magnet M365, this circuit extending from the grounded vertical conductor C305 by way of the contacts 347 and M365 to battery. When energized over the above-traced circuit the vertical magnet M365 operates to drive the first and second wiper sets of the mechanism 310 one step in the vertical direction and to complete, at the contacts 366, an obvious path for applying ground potential to the interrupter conductor C306. The application of ground potential to the interrupter conductor C306 causes the distributor 301 to interrupt the application of ground potential to the vertical conductor C305; whereupon the vertical magnet M365 restores to interrupt, at the contacts 366, the previously mentioned path for applying ground potential to the interrupter conductor C306. Accordingly, the vertical magnet M365 operates intermittently, thereby to drive the first and second wiper sets of the mechanism 310 step by step in the vertical direction until the control wiper 318 engages a contact in the associated vertical contact bank having direct ground potential thereon; whereupon an obvious path is completed for applying ground potential to the test conductor C307 extending to the distributor 301. In the present instance the first and second wiper sets of the mechanism 310 are driven only one step in the vertical direction; whereupon the vertical control wiper 318 engages the first contact in the associated vertical control contact bank having ground potential thereon. The application of ground potential to the test conductor C307 causes the distributor 301 to operate, thereby to interrupt the application of ground potential to the vertical conductor C305 and to apply ground potential to the rotary conductor C304. The application of ground potential to the rotary conductor C304 completes the

previously mentioned circuit for energizing the rotary magnet M367, this circuit extending from the grounded rotary conductor C304 by way of the contacts 346, 330 and 328 and M367 to battery. When energized over the above-traced circuit the rotary magnet M367 operates to drive the first and second wiper sets of the mechanism 310 one step in the rotary direction and to complete, at the contacts 368, an obvious path for applying ground potential to the interrupter conductor C306. This application of ground potential to the interrupter conductor C306 causes the distributor 301 to remove the application of ground potential to the rotary conductor C304, whereupon the rotary magnet M367 restores to interrupt, at the contacts 368, the previously mentioned path for applying ground potential to the interrupter conductor C306. Accordingly the rotary magnet M367 operates intermittently, thereby to drive the first and second wiper sets of the mechanism 310 step by step in the rotary direction until either the control wiper 313 or the control wiper 316 of the respective first and second wiper sets engages the control conductor of a calling telephone line having battery potential thereon. In the present example the telephone line 225 is included in the first section of the main contact bank of the mechanism 310.

Accordingly, when the control wiper 313 of the first wiper set of the mechanism 310 engages the contact of the contact set in the first section of the main contact bank of the mechanism 310 terminating the control conductor C228 of the telephone line 225, a circuit is completed for energizing the upper winding of the switching relay R320. This circuit extends from ground by way of the contacts 221, 215 and 214, the start conductor C230, the control wiper 318, the upper winding of R320, the control wiper 313, the control conductor C228 of the telephone line 225, the contacts 213 and the intermediate winding of R210 to battery. When energized over the above-traced circuit the switching relay R320 operates exceedingly fast, thereby to complete, at the contacts 325, a holding circuit for energizing the intermediate winding thereof, this circuit extending from the grounded control conductor C363 of the trunk 360 by way of the contacts 336 and 325 and the intermediate winding of R320 to battery. Also, upon operating, the switching relay R320 interrupts, at the contacts 328, a point in the previously traced circuit for energizing the rotary magnet M367, thereby positively to arrest further operation of the mechanism 310. Further the switching relay R320 interrupts, at the contacts 326, a point in a circuit traced hereinafter for energizing the upper winding of the switching relay R330, thereby positively to prevent operation of the latter relay at this time. Also the switching relay R320 interrupts, at the contacts 321, a point in a circuit traced hereinafter for energizing the release magnet M369 and completes, at the contacts 327, a connection between the rotary conductor C304 and the guard conductor C303; this connection extending from the rotary conductor C304 by way of the contacts 346, 330, 327 and 344 to the guard conductor C303. When the rotary conductor C304 is connected to the guard conductor C303 operation of the distributor 301 to control the finder switch 300 is arrested, whereupon the distributor 301 operates automatically to select for use another idle one of the links in the first group of links.

Also it is noted that when the carriage of the

mechanism 310 is driven one step in the vertical direction the sets of switch springs S370, S371 and S372 are actuated. More particularly, the set of switch springs S370 is actuated into engagement, thereby to prepare a further point in the previously mentioned circuit for energizing the release magnet M369; while the set of switch springs S372 is actuated into disengagement, thereby to interrupt a further point in the previously traced path for applying ground potential to the all-link-busy conductor C309. Finally the contacts 372 of the set of switch springs S371 are actuated into engagement, thereby to prepare a path traced hereinafter for applying ground potential to the guard conductor C303. 15 Finally, upon operating the switching relay R320 completes, at the contacts 322, 323 and 324, connections between the conductors of the trunk 360 extending between the finder switch 300 and the selector switch 600 in the first wiper set of the mechanism 310. More particularly, a low resistance circuit is completed, at the contacts 324, for energizing the intermediate winding of the line and cutoff relay R210, this circuit extending from the grounded control conductor C363 of the 20 trunk 360 by way of the contacts 336 and 324, the wiper 313, the control conductor C228 of the telephone line 225, the contacts 213 and the intermediate winding of R210 to battery. When the intermediate winding of the line and cutoff relay R210 is thus energized this relay operates completely, thereby to interrupt, at the contacts 215, the previously traced path for applying ground potential to the start conductor C230 extending to the marking network 305 in order to arrest operation of the distributor 301. Further the line and cutoff relay R210 interrupts, at the contacts 211 and 212, the previously traced circuit for energizing the windings thereof across the line conductors C226 and C227 of the telephone line 225, thereby to clear the telephone line 225 of impedance elements. At this time ground potential appearing upon the control conductor C228 of the telephone line 225 is applied to the control conductor C229 thereof, thereby to mark the telephone line 225 as busy to the B operator positions in the local exchange 20.

Further it is noted that the distributor 301 operates in order to select another idle link in the first group of links for use only in the event ground potential appears upon the all-link-busy conductor C309 in at least one of the finder switches of the links in the first group of links, ground potential being removed from the all-link-busy conductor C309 in the finder switch 300 of the first link 100 in the first group of links at this time due to the operated condition of the set of switch springs S372, as previously noted. Also ground potential is applied to the guard conductor C303 in the finder switch 300, thereby to prevent the distributor 301 from preselecting the first link 100 illustrated at this time due to the busy condition of the finder switch 300. The path for applying ground potential in the finder switch 300 to the guard conductor C303 extends from ground by way of the contacts 372 of the set of switch springs S371 and the contacts 345 to the guard conductor C303, the start relay R340 being restored at this time. Further it is noted that the start relay R340 is of the slow-to-release type and restores shortly after the distributor 301 is released. Upon restoring the start relay R340 interrupts, at the contacts 342, the previously traced path for applying ground potential to the control conductor C363 of the

trunk 360, ground potential being applied to the control conductor C363 of the trunk 360 in the selector switch 600 at this time. Further the start relay R340 interrupts, at the contacts 343, the previously mentioned multiple circuit for energizing the lower windings of the switching relays R320 and R330, the switching relay R320 being retained in its operated position at this time due to the completed holding circuit for energizing the intermediate winding thereof.

When the trunk 360 is connected to the telephone line 225 a loop circuit is completed for energizing in series the upper and lower windings of the error relay R650 and the upper and lower windings of the line relay R655 in the selector switch 600. This circuit extends from ground by way of the lower winding of R655, the lower winding of R650, the line conductor C662 of the trunk 660, the contacts L556, C502, the contacts 556, C411, the contacts 456, the line conductor C362 of the trunk 360, the contacts 334 and 323, and the wiper 312 to the line conductor C227 of the telephone line 225; and from battery by way of the upper winding of R655, the upper winding of R650, the line conductors C661 of the trunk 660, the contacts L553, C501, the contacts 553, C410, the contacts 453, the line conductor C361 of the trunk 360, the contacts 332 and 322, and the wiper 311 to the line conductor C226 of the telephone line 225; the line conductors C226 and C227 of the telephone line 225 being connected together by way of the bridge path at the subscriber substation T1. When the upper and lower windings of the error relay R650 are thus energized, this relay remains in its restored position, it being of the differential type. On the other hand, when the upper and lower windings of the line relay R655 are thus energized, this relay operates to complete, at the contacts 656, 40 a circuit for energizing the winding of the hold relay R660, this circuit extending from ground by way of the contacts 615 and 656 and the winding of R660 to battery. When thus energized, the hold relay R660 operates to complete, at the contacts 662, a multiple path for applying ground potential to the control conductor C363 of the trunk 360 as previously noted. The multiple path for applying ground potential to the control conductor C363 of the trunk 360 extends from 45 ground by way of the contacts 662, 654 and 627 and the control conductor C663 of the trunk 660 to the control conductor C363 of the trunk 360. Also, the hold relay R660 completes, at the contacts 663, an obvious circuit for energizing the lower winding of the switching relay R670, thereby to render the switching relay R670 exceedingly fast to operate when the upper winding thereof is energized. Further, the hold relay R660 prepares, at the contacts 661, a circuit traced hereinafter for energizing the upper winding of the switching relay R670 and prepares, at the contacts 664, a circuit traced hereinafter for energizing in multiple the lower winding of the transfer relay R665 and the vertical magnet M614.

Also, upon operating, the hold relay R660 completes, at the contacts 662, a circuit for energizing the upper winding of the transfer relay R665, this circuit extending from ground by way of the contacts 662, the set of switch springs S620 and the upper winding of R665 to battery. When thus energized, the transfer relay operates to prepare, at the contacts 667, a further point in the previously mentioned multiple circuit for energizing the lower winding thereof.

and the vertical magnet M614 and to interrupt, at the contacts 669', a point in a circuit traced hereinafter for energizing the rotary magnet M616. Finally, upon operating, the transfer relay R665 completes, at the contacts 666, an obvious path for applying ground potential to the control conductor C664 of the trunk 660. The application of ground potential to the control conductor C664 of the trunk 660 initiates operation of the first switching unit in one of the groups of switching units as determined by the A operator position distributor 830 in a manner more fully described hereinafter.

Before continuing with the operation of the first switching unit in one of the groups of switching units it is noted that the A operator position distributor 830 is operative to preselect one of the groups of switching units corresponding to an idle one of the A operator positions. Assuming that the first group of switching units associated with the first A operator position 700 has been previously selected at this time by the A operator position distributor 830 due to the idle condition of the first A operator position 700, a holding circuit is completed for energizing in series the winding of the control relay R835 and the right-hand winding of the position relay R850, the position relay R850 corresponding to the first group of switching units and to the first A operator position 700. This circuit extends from ground by way of the winding of R835, the contacts 864 and 853 and the right-hand winding of R850 to battery. The operated position relay R850 retains interrupted, at the contacts 854, a holding circuit traced hereinafter for energizing the winding of the control relay R835 in series with the right-hand winding of the position relay R870 and retains prepared, at the contacts 852, a path for applying battery potential to the control conductor C884 in the distributor trunk 880. The path for applying battery potential to the control conductor C884 in the distributor trunk 880 extends from battery by way of the resistor 812 and the contacts 852 to the control conductor C884 in the distributor trunk 880. Finally, the operated position relay R850 retains prepared, at the contacts 851, a point in a circuit traced hereinafter for energizing the left-hand winding of the position relay R860 corresponding to the second A operator position. The application of battery potential to the control conductor C884 in the distributor trunk 880 prepares multiple circuits for initiating operation of each switching unit in the first group of switching units, thereby to select the first group of switching units and the corresponding first A operator position 700.

Continuing now with the operation of one of the switching units in the first group of switching units, it is noted that the first switching unit 400 in the first group of switching units is operated at this time, this particular switching unit being operated at this time due to the facts that only the first group of switching units is prepared to be operated and that the first switching unit 400 in the first group of switching units is associated with the first link 100 in the first group of links. Accordingly, at this time, when ground potential is applied to the control conductor C664 of the trunk 660 a circuit is completed for energizing the upper winding of the feeder relay R450, this circuit extending from the grounded control conductor C664 of the trunk 660 by way of the contacts L559, 559 and 459, the upper winding of R450, C496 and

the contacts 431 to the control conductor C884 in the distributor trunk 880, the control conductor C884 in the distributor trunk 880 having battery potential thereon as previously noted. At this point it is noted that the application of ground potential to the control conductor C664 of the trunk 660 prepares an obvious multiple circuit for energizing the upper winding of the feeder relay R550 included in the first switching unit 500 in the second group of switching units, an obvious multiple circuit for energizing the upper winding of the feeder relay LR550 included in the first switching unit L500 in the last group of switching units, etc. However, only the feeder relay R450 included in the first switching unit 400 in the first group of switching units is operated at this time due to the fact that battery potential by way of the resistor 812 in the A operator position distributor 830 only appears upon the control conductor C884 in the distributor trunk 880 at this time. Further, it is noted that the application of battery potential to the control conductor C884 in the distributor trunk 880 prepares obvious multiple circuits for energizing the upper windings of the feeder relays included in the other switching units in the first group of switching units. However, only the feeder relay R450 in the first switching unit 400 in the first group of switching units is operated due to the fact that the first link 100 is the only link in the first group of links which is operating at this time.

Upon operating, the feeder relay R450 completes, at the contacts 458, a holding circuit for energizing the lower winding thereof in series with the winding of the start relay R430, this circuit extending from ground by way of the lower winding of R450, the contacts 458, C497 and the winding of R430 to battery. When this holding circuit is completed the feeder relay R450 remains in its operated position, while the start relay R430 operates. Also, upon operating, the feeder relay R450 interrupts, at the contacts 459, the previously mentioned prepared multiple circuits for energizing the upper windings of the feeder relays included in the first switching units in the other groups of switching units. Similarly, upon operating, the start relay R430 interrupts, at the contacts 431, the previously mentioned prepared multiple circuits for energizing the upper windings of the feeder relays included in the first switching unit in the first group of switching units. Also, upon operating, the start relay R430 completes, at the contacts 432, an obvious connection between the control conductors C881 and C884 in the distributor trunk 880, the control conductor C884 having battery potential thereon; as previously noted, and the control conductor C884 having ground potential thereon by way of the contacts 831. Accordingly, when the control conductors C881 and C884 in the distributor trunk 880 are connected together, an obvious circuit is completed for loading the battery in the A operator position distributor 830 by way of the resistor 812, thereby effectively to remove battery potential from the control conductor C884 in the distributor trunk 880. The effective removal of battery potential from the control conductor C881 in the distributor trunk 880 positively prevents operation of any of the other switching units in the first group of switching units at this time.

Also, upon operating, the start relay R430 completes, at the contacts 433, a path for applying ground potential to the control conductor C883

in the distributor trunk 830, this path extending from ground by way of the contacts 441 and 433 to the control conductor C883 in the distributor trunk 880. The application of ground potential to the control conductor C883 in the distributor trunk 880 completes the previously mentioned circuit for energizing the left-hand winding of the position relay R860 in the A operator position distributor 830, this circuit extending from the grounded control conductor C883 in the distributor trunk 880 by way of the contacts 851 and the left-hand winding of R860 to battery. When thus energized, the position relay R860 operates to complete, at the contacts 863, a holding circuit for energizing in series the winding of the control relay R835 and the right-hand winding of R860, this holding circuit extending from ground by way of the winding of R835, the contacts 874 and 863 and the right-hand winding of R860 to battery. Also, upon operating, the position relay R860 prepares, at the contacts 862, an obvious path for subsequently applying battery potential to the control conductor C883 in the distributor trunk 880 and prepares, at the contacts 861, a circuit traced hereinafter for energizing the left-hand winding of the position relay R870. Finally, the position relay R860 interrupts, at the contacts 864, the previously traced holding circuit for energizing in series the winding of the control relay R835 and the right-hand winding of the position relay R850, thereby to cause the position relay R850 to restore. Upon restoring, the position relay R850 interrupts, at the contacts 853, a further point in the previously traced series holding circuit for energizing the right-hand winding thereof and the winding of the control relay R835, and interrupts, at the contacts 852, the previously traced connection between the control conductor C881 in the distributor trunk 880 and battery in the A operator position distributor 830, thereby to cause effective battery potential to be applied by way of the resistor 812 and the contacts 862 to the control conductor C883 in the distributor trunk 880. Also, upon restoring, the position relay R850 interrupts, at the contacts 851, the previously traced circuit for energizing the left-hand winding of the position relay R860 and prepares, at the contacts 854, a holding circuit traced hereinafter for energizing in series the winding of the control relay R835 and the right-hand winding of the position relay R870. Accordingly, at this time, effective battery potential is applied by way of the resistor 812 in the A operator position distributor 830 to the control conductor C883 in the distributor trunk 880. The application of battery potential to the control conductor C883 in the distributor trunk 880 prepares the switching units in the second group of switching units to be operative, thereby to select the second A operator position to receive the next incoming call.

Also, upon operating, the start relay R430 completes, at the contacts 434, an obvious connection between the control conductors C882 and C890 in the distributor trunk 880, thereby to prepare a point in a chain circuit traced hereinafter for energizing the winding of the busy relay R839 in the A operator position distributor 830 for a purpose more fully described hereinafter.

Also, upon operating, the feeder relay R450 completes, at the contacts 451, 452, 454 and 455, an alternative connection between the finder switch 300 and the selector switch 600, including the feeder trunk 480, and interrupts, at the con-

tacts 453 and 456, the previously traced direct connection between the finder switch 300 and the selector switch 600. More particularly, at this time, the line conductor C361 of the trunk 360 is connected by way of the contacts 452, the line conductor C482 of the feeder trunk 480, the contacts 453, the line conductor C481 of the feeder trunk 480 and the contacts 451 to the conductor C410, and therefrom by way of the previously traced path to the line conductor C661 of the trunk 660; while the line conductor C362 of the trunk 360 is connected by way of the contacts 455, the line conductor C484 of the feeder trunk 480, the contacts 466, the line conductor C483 of the feeder trunk 480 and the contacts 454 to the conductor C411, and therefrom by way of the previously traced path to the line conductor C662 of the trunk 660.

Also, upon operating, the start relay R430 completes, at the contacts 435, a circuit for energizing the rotary magnet M419 of the sequence switch 410, this circuit extending from ground by way of the contacts 435, 442 and 429 and M419 to battery. When thus energized, the rotary magnet M419 operates to interrupt, at the contacts 420, the previously traced circuit for energizing the rotary magnet M419, thereby to cause the rotary magnet M419 to restore and recomplete, at the contacts 420, the previously traced circuit for energizing the rotary magnet M419. Accordingly, the rotary magnet M419 operates intermittently, thereby to drive the wipers noted of the sequence switch 410 step by step in the clockwise direction. Also, upon operating, the start relay R430 prepares, at the contacts 435, a circuit traced hereinafter for energizing the winding of the stop relay R440.

The rotary magnet M419 continues to operate intermittently in order to drive the wipers noted of the sequence switch 410 step by step in the clockwise direction until the wiper 415 thereof engages the seventh contact in the associated contact bank 416 terminating the marking conductor C877 in the marking trunk 870 extending to the first call storage unit 800, whereupon a circuit is completed for energizing in series the winding of the stop relay R440 and the winding of the marking relay 1M. This circuit extends from ground by way of the contacts 435, the winding of R440, the wiper 415 and engaged seventh contact in the associated contact bank 416 of the sequence switch 410, the marking conductor C877 in the marking trunk 870, the contacts 811 and the winding of 1M to battery. When this series circuit is completed the stop relay R440 operates immediately and the marking relay 1M operates shortly thereafter, the latter relay being of the slow-to-operate type. Upon operating, the stop relay R440 interrupts, at the contacts 442, the previously traced circuit for energizing the rotary magnet M419 of the sequence switch 410, thereby to arrest further operation of the rotary magnet M419 at this time. Upon operating, the marking relay 1M completes, at the contacts 1M2, an obvious circuit for energizing the lower winding of the control relay R810, thereby to cause the latter relay to operate and interrupt, at the contacts 811, the previously traced circuit for energizing in series the winding of the stop relay R440 and the winding of the marking relay 1M, whereupon the stop relay R440 and the marking relay 1M restore. Upon restoring, the stop relay R440 recompletes, at the contacts 442, the previously traced circuit for energizing the rotary magnet M419 of the sequence switch 410, thereby

to cause the rotary magnet M419 to reoperate and drive the wipers noted of the sequence switch an additional step in the clockwise direction. Upon restoring, the marking relay 1M interrupts, at the contacts 1M2, the previously mentioned circuit for energizing the lower winding of the control relay R810, thereby to cause the latter relay to restore and reprepare, at the contacts 811, the previously traced circuit for energizing the winding of the marking relay 1M. When the wiper 415 of the sequence switch 410 is driven an additional step in the clockwise direction into engagement with the eighth contact in the associated contact bank 416 of the sequence switch 410 a series circuit is completed for energizing the winding of the stop relay R440 and the winding of the start relay R710, this circuit extending from ground by way of the contacts 433, the winding of R440, the wiper 415 and engaged eighth contact in the associated contact bank 416 of the sequence switch 410, the control conductor C492 in the control trunk 490 and the winding of R710 to battery. When this series circuit is completed the stop relay R440 reoperates, thereby to arrest further operation of the rotary magnet M419 of the sequence switch 410, as previously noted, while the start relay R710 operates.

Upon operating, the start relay R710 completes, at the contacts RA771, a circuit for energizing the winding of the position relay R460, this circuit extending from ground by way of the contacts RA771, the control conductor C493 in the control trunk 490, the wiper 417 and engaged eighth contact in the associated contact bank 418 of the sequence switch 410 and the winding of R460 to battery. When thus energized the position relay R460 operates to complete, at the contacts 461, 462, 464 and 465, a connection between the finder switch 300 and the selector switch 600, including the position trunk 470 extending to the first A operator position 700, and to interrupt, at the contacts 463 and 466, the previously traced alternative connection between the finder switch 300 and the selector switch 600. More particularly, the line conductor C361 of the trunk 360 is connected by way of the contacts 452, the line conductor C482 of the feeder trunk 480, the contacts 462, the line conductor C474 of the position trunk 470, the contacts 731, the retarder coil 730, the contacts 733, the line conductor C475 of the position trunk 470, the contacts 465, the line conductor C484 of the feeder trunk 480, and the contacts 455 to the line conductor C362 of the trunk 360; while the conductor C410, connected by way of the previously traced path to the line conductor C361 of the trunk 360, is connected by way of the contacts 451, the line conductor C421 of the feeder trunk 480, the contacts 451, the line conductor C473 of the position trunk 470, the contacts 736, the retarder coil 530, the contacts 738, the line conductor C472 of the position trunk 470, the contacts 464, the line conductor C483 of the feeder trunk 480, and the contacts 454 to the conductor C411, the conductor C411 being connected by way of the previously traced path to the line conductor C662 of the trunk 660. Accordingly, at this time, the finder switch 300 is connected by way of the previously traced circuit including the first A operator position 700 to the selector switch 600. Further, it is noted that the line conductors C473 and C474 of the position trunk 470 are connected by way of the contacts 736, 731 and 716, the windings 703 and 704 of the repeater 701, the contacts 718 and the

contacts 738 and 733 to the line conductors C472 and C475 of the position trunk 470.

Also, upon operating, the start relay R710 completes, at the contacts RA774, an obvious connection between the control conductors C381 and C883 in the distributor trunk 880, thereby to prepare an obvious alternative circuit for energizing the left-hand winding of the position relay R860 so long as the busy relay R830 in the A operator position distributor 830 remains restored. Accordingly, so long as the busy relay R830 remains restored, operation of the position relay R859 is effective to complete, at the contacts 851, the previously mentioned alternative circuit for energizing the left-hand winding of the position relay R860. Hence, the A operator position distributor 830 is not operative to select the first group of switching units and, consequently, the first A operator position 700 so long as the first A operator position 700 is busy, the start relay R710 being operated while the first A operator position 700 is busy, unless all of the A operator positions are also busy, in which event the busy relay R830 in the A operator position distributor 830 is operated due to the completion of the previously mentioned chain circuit, as will be more fully explained subsequently.

Continuing now with the operation of the apparatus at the first A operator position 700 incident to the seizure of the position trunk 470 extending thereto, it is noted that when the start relay R710 operates it also completes, at the contacts RA773, an obvious path for applying ground potential to the control conductor C728. The application of ground potential to the control conductor C728 completes a circuit for energizing the winding of the tone relay R715, this circuit extending from the grounded control conductor C728 by way of the contacts 728 and the winding of R715 to battery. When the winding of the tone relay R715 is thus energized this relay operates shortly thereafter, this relay being of the slow-to-operate type. Upon operating the tone relay R715 completes, at the contacts 716', an obvious circuit for energizing the winding of the tone relay R720, thereby to cause the latter relay to operate shortly thereafter, the latter relay being of the slow-to-operate type. Upon operating the tone relay R720 completes, at the contacts 723, an obvious circuit for energizing the winding of the tone relay R725, thereby to cause the latter relay to operate shortly thereafter, the latter relay being of the slow-to-operate type. Upon operating the tone relay R725 completes, at the contacts 727, an obvious holding circuit for energizing the winding thereof and interrupts, at the contacts 728, the previously traced circuit for energizing the winding of the tone relay R715, thereby to cause the latter relay to restore. Upon restoring the tone relay R715 interrupts, at the contacts 716', the previously mentioned circuit for energizing the winding of the tone relay R720, thereby to cause the latter relay to restore.

Assuming that the plugs associated with the transmitter 708 and the receiver 707 are inserted into the associated jacks J706 and J705 at this time, a circuit is completed for energizing in series the transmitter 708 and the control relay R710. This circuit extends from ground by way of the winding 702 of the repeater 701, the jack 705 and associated plug, the transmitter 708, the plug and associated jack J706 and the winding of R710 to battery. When the winding of the control relay R710 is thus energized it operates to interrupt, at the contacts 711, an obvious path

for applying ground potential to the control conductor C883 in the distributor trunk 880. At this point it is noted that when the plugs associated with the receiver 707 and the transmitter 708 are withdrawn from the associated jacks J705 and J706, the previously traced circuit for energizing the winding of the control relay R710 is interrupted, thereby to cause the latter relay to restore; whereupon the previously mentioned path for applying ground potential to the control conductor C883 in the distributor trunk 880 is completed. When ground potential is applied to the control conductor C883 in the distributor trunk 880, the first A operator position 700 is marked against selection by the A operator position distributor 830 in an obvious manner. Hence it will be understood that the first A operator position 700 is selectable by the A operator position distributor 830 only when the plugs associated with the receiver 707 and the transmitter 708 are inserted into the associated jacks J705 and J706.

Also at this time the receiver 707 is operatively associated with the winding 704 of the repeater 701 by way of a circuit extending from one terminal of the receiver 707 over the plug and associated jack J706, the winding 704 and the jack J705 and associated plug to the other terminal of the receiver 707.

It is noted that prior to the operation of the tone relays R715, R720 and R725 the windings 703 and 704 of the repeater 701 are connected by way of the contacts 716 and 718 across the retarder coil 730 and consequently to the loop circuit extending between the first A operator position 700 and the calling subscriber substation T1 and to the loop circuit extending between the first A operator position 700 and the line relay R655 in the selector switch 600. Accordingly, when the tone relay R715 operates, it interrupts, at the contacts 716 and 718, the previously traced connection between the windings 702 and 704 of the repeater 701 and the retarder coil 730 and completes, at the contacts 717 and 719, a circuit including the windings 703 and 704 of the repeater 701 for charging the condenser 709. This circuit for charging the condenser 709 extends from the ungrounded terminal of a grounded source of tone current by way of the conductor C712, the contacts 722 and 717, the windings 703 and 704 of the repeater 701, the contacts 719 and the condenser 709 to ground. Upon operating the tone relay R720 it interrupts, at the contacts 722, the above-traced circuit for charging the condenser 709 and prepares, at the contacts 721, an alternative circuit for charging the condenser 709. Upon operating the tone relay R725 completes, at the contacts 726, the alternative circuit for charging the condenser 709, this circuit extending from the tone conductor C712 by way of the contacts 726, 721, 717, the windings 703 and 704 of the repeater 701, the contacts 719 and the condenser 709 to ground. Finally when the tone relay R715 restores it interrupts, at the contacts 717 and 719, the above-traced alternative circuit for charging the condenser 709 and re-completes, at the contacts 716 and 718, the interconnection between the repeater 701 and the loop circuits respectively extending to the calling subscriber substation T1 and to the line relay R655 in the selector switch 600. The alternate completion and interruption of the circuits for charging the condenser 709, including the tone conductor C712, causes the winding 704 of the repeater 701 to be alternately energized and deenergized with tone current, thereby to cause the receiver 707 at the

first A operator position 700 to be alternately operated, whereupon a distinct zip-zip tone is produced thereby. The production of the zip-zip tone by the receiver 707 at the first A operator position 700 indicates to the operator thereat that an incoming call has been extended to her position by one of the switching units in the first group of switching units.

Finally, upon operating the start relay R770 completes, at the contacts RA773, a circuit for illuminating the flat rate signal lamp L880, in the present instance the signal relays R885 and R890 being restored at this time. The circuit for illuminating the flat rate signal lamp L880 extends from ground by way of the contacts RA773 and 886 and L880 to battery. The illumination of the flat rate signal lamp L880 indicates to the operator at the first A operator position 700 that the incoming call which is extended to her position originates at a subscriber substation to which flat rate service is rendered and that it is not necessary to register the call.

At this time both the receiver 707 and the transmitter 708 at the first A operator position 700 are operatively connected to the loop circuit extending to the calling subscriber substation T1. Accordingly the operator at the first A operator position 700 may converse with the subscriber at the calling subscriber substation T1 and ascertain the destination of the call. After learning the destination of the call the operator at the first A operator position 700 initiates the extension of the call by operating the key sender K720 in order appropriately to control the selector switch 600.

Extension of a call from an A operator position

In order to extend a call from an A operator position, such, for example, as a call from the subscriber substation T1 to the first A operator position 700, the operator at the first A operator position 700 operates the key sender K720, thereby to cause the impulse relay R740 to operate. Upon operating the impulse relay R740 prepares, at the contacts 741 and 743, an alternative loop circuit substantially identical to that previously traced between the line relay R655 in the selector switch 600 and the key sender K720 and completes, at the contacts 745, an obvious circuit for energizing the winding of the front split relay R735, thereby to cause the latter relay to operate. Upon operating, the front split relay R735 interrupts, at the contacts 736 and 738, the previously traced loop circuit between the retarder coil 730 and the line relay R655 in the selector switch 600 and completes, at the contacts 731 and 739, the previously mentioned alternative loop circuit between the key sender K720 and the line relay R655 in the selector switch 600. The key sender K720 then operates to interrupt intermittently the previously mentioned alternative loop circuit extending to the selector switch 600, thereby to cause the line relay R655 to follow the impulses of the digit transmitted in the usual manner. Each time the line relay R655 restores, it interrupts, at the contacts 656, the previously traced circuit for energizing the winding of the hold relay R660 and completes, at the contacts 657, the previously mentioned multiple circuit for energizing the lower winding of the transfer relay R665 and the vertical magnet M614. This circuit extends from ground by way of the contacts 675, 657, 664 and 667 and the lower winding of R665 to battery, and from the contacts 667 and the vertical magnet M614 to

battery. Due to the fact that the hold relay R660 and the transfer relay R665 are of the slow-to-release type, these relays remain operated during impulsing. Each time the vertical magnet M614 is energized it operates, thereby to drive the wiper set of the mechanism 610 one step in the vertical direction. When the wiper set of the mechanism 610 is driven one step in the vertical direction the set of switch springs S620 is actuated into disengagement, thereby to interrupt the previously traced circuit for energizing the upper winding of the transfer relay R665; the set of switch springs S619 is actuated into engagement, thereby to prepare a circuit traced hereinafter for energizing the release magnet M618; and the set of switch springs S621 is actuated into engagement, thereby to prepare a circuit traced hereinafter for energizing the rotary magnet M616.

At the conclusion of the digit transmitted by the key sender K720 the impulse relay R740 restores, thereby to interrupt, at the contacts 745, the previously mentioned circuit for energizing the winding of the front split relay R735. The front split relay R735 then restores to interrupt, at the contacts 737 and 739, the previously mentioned alternative loop circuit extending between the key sender K720 and the selector switch 600 and to complete, at the contacts 736 and 738, the previously traced loop circuit between the retarder coil 730 and the line relay R655 in the selector switch 600. Shortly following the conclusion of the digit transmitted from the key sender K720 to the selector switch 600 the transfer relay R665 restores to interrupt, at the contacts 661, a further point in the previously traced multiple circuit for energizing the lower winding thereof and the vertical magnet M614 and to complete, at the contacts 669, the previously mentioned circuit for energizing the rotary magnet M616. This circuit extends from ground by way of the contacts 675, 656, 617 and 669, the set of switch springs S621 and M616 to battery. When thus energized the rotary magnet M616 operates to drive the wiper set of the mechanism 610 one step in the rotary direction and to interrupt, at the contacts 617, the previously traced circuit for energizing the rotary magnet M616, thereby to cause the rotary magnet M616 to restore. Upon restoring the rotary magnet M616 recomplete, at the contacts 617, the previously traced circuit for energizing the rotary magnet M616. Accordingly the rotary magnet M616 operates intermittently, thereby to drive the wiper set of the mechanism 610 step by step in the rotary direction until the wiper 613 of the wiper set engages a contact terminating the control conductor of a trunk having battery potential thereon, battery potential being present upon the control conductor of the trunk in the event the trunk is idle, whereupon a circuit is completed for energizing the upper winding of the switching relay R670. The circuit for energizing the upper winding of the switching relay R670 extends from ground by way of the contacts 662, the upper winding of R670, the contacts 661 and the wiper 613 to the control conductor of the trunk having battery potential thereon.

When this circuit is completed the switching relay R670 operates exceedingly fast, thereby to complete, at the contacts 674, a holding circuit for energizing the intermediate winding thereof, this circuit extending from ground by way of

the contacts 662 and 674 and the intermediate winding of R670 to battery. Also upon operating the switching relay R670 interrupts, at the contacts 675, the previously traced circuit for energizing the rotary magnet M616, thereby positively to arrest further operation of the wiper set of the mechanism 610. Further the switching relay R670 interrupts, at the contacts 675, the previously traced circuit for energizing the winding of the hold relay R660, thereby to cause the latter relay to restore shortly thereafter. Finally the switching relay R670 completes, at the contacts 671, 672 and 673, a connection between the selector switch 600 and the trunk seized by the wiper set of the mechanism 610, thereby to complete a loop circuit for energizing in series the upper and lower windings of the battery supply relay R630. This loop circuit extends from ground by way of the lower winding of R630, the contacts 672 and the wiper 612 to one of the line conductors of the seized trunk and from battery by way of the upper winding of R630, the contacts 671 and the wiper 611 to the other line conductor of the seized trunk, the line conductors of the seized trunk being connected together at the operator position terminating the seized trunk. When thus energized the battery supply relay R630 operates to complete, at the contacts 633, an obvious circuit for energizing the winding of the control relay R640, thereby to cause the latter relay to operate shortly thereafter, the latter relay being of the slow-to-operate type. Upon operating the control relay R640 completes, at the contacts 641, an obvious alternative path for applying ground potential to the control conductor C363 of the trunk 360. Further it is noted that the loop circuit extending between the repeater 701 and the line relay R655 in the selector switch 600 is operatively connected by the condensers 628 and 629 to the loop circuit extending between the battery supply relay R630 in the selector switch 600 and the trunk seized by the wiper set of the mechanism 610.

In the event the call which is extended from the first A operator position 700 is ultimately to be completed in the local exchange 20 the operator at the first A operator position 700 controls the key sender K720, thereby to cause the selector switch 600 to seize an idle trunk in the group of trunks extending to an idle one of the B operator positions in the local exchange 20. For example, the selector switch 600 may be controlled to seize an idle one of the trunks, such, for example, as the trunk 690 in the group of trunks extending to the idle first B operator position 694 in the local exchange 20. The trunk 690 extending to the first B operator position 694 is marked for seizure by the presence of battery potential upon the control conductor C693 thereof, the path for applying battery potential to the control conductor C693 of the trunk 690 extending from battery by way of the winding of the line relay R680 and the contacts 686 to the control conductor C693. When the switching relay R670 operates it completes, at the contacts 673, an obvious path for applying ground potential by way of the wiper 613 to the control conductor C693 of the trunk 690, thereby to complete an obvious circuit for energizing the winding of the line relay R680. When thus energized the line relay R680 operates to interrupt, at the contacts 681, a circuit for energizing the busy relay R685. Accordingly, at

this time a loop circuit is completed between the battery supply relay R630 in the selector switch 600 and the first B operator position 694. When the trunk 690 is seized by the selector switch 600 a signal is transmitted to the first B operator position 694; whereupon the operator at the first B operator position 694 answers the call and communicates with the operator at the first A operator position 700 concerning the extension of the call to a called subscriber substation in the local exchange 20. The operator at the first B operator position 694 then proceeds to extend the call to the called subscriber substation in the local exchange 20 in the usual manner.

At this point it is noted that the operator at the first B operator position 694 may render the trunk 690 extending thereto busy by causing battery potential to be applied to the line conductor C692 of the trunk 690 prior to seizure of the trunk 690. The application of battery potential to the line conductor C692 of the trunk 690 completes an obvious circuit for energizing the winding of the busy relay R685, thereby to cause the latter relay to operate. Upon operating, the busy relay R685 interrupts, at the contacts 686, the previously traced path for applying battery potential by way of the winding of the line relay R680 to the control conductor C693 of the trunk 690, and completes, at the contacts 687, an obvious path for applying ground potential to the control conductor C693 of the trunk 690, the application of ground potential to the control conductor C693 of the trunk 690 being effective to mark the trunk 690 as busy to the selector switches having access thereto.

Reconsidering now the operation of the selector switch 600 it is noted that in the event the call which is extended from the first A operator position 700 is ultimately to be completed in the distant exchange 30, the operator at the first A operator position 700 controls the key sender K720, thereby to cause the selector switch 600 to seize an idle one of the trunk lines, such for example, as the trunk line 670 in the group of trunk lines extending between the local exchange 20 and the B operator position 698 in the distant exchange 30, thereby to cause the trunk line circuit 672 individually associated with the trunk line 670 to operate in a manner similar to the trunk line circuit 680 previously described. When the trunk line 670 is seized by the selector switch 600 a signal is transmitted to the B operator position 698 in the distant exchange 30; whereupon the operator at the B operator position 698 answers the call and is advised by the operator at the first A operator position 700 concerning the extension of the call to a subscriber substation in the distant exchange 30. The operator at the B operator position 698 then extends the call to the called subscriber substation in the distant exchange 30 in the usual manner.

Considering further the operation of the selector switch 600 it is noted that in the event the call which is extended from the first A operator position 700 is a toll call, the operator at the first A operator position 700 controls the key sender K720 thereby to cause the selector switch 600 to seize an idle one of the trunks in one of the groups of trunks extending to an idle one of the toll operator positions, such, for example, as the trunk 695 in the group of trunks extending to the toll operator position 699, thereby to cause the trunk line circuit 697 indi-

vidually associated with the trunk 695 to operate in a manner similar to the trunk line circuit 680 previously described. When the trunk 695 is seized by the selector switch 600 a signal is transmitted to the toll operator position 699; whereupon the operator at the toll operator position 699 answers the call and is advised by the operator at the first A operator position 700 concerning the routing of the call. The operator at the toll operator position 699 then routes the call toll in the usual manner.

Again considering the operation of the selector switch 600 to extend the call from the first A operator position 700 to the first B operator position 694, it is noted that when the battery supply relay R630 operates it prepares, at the contacts 631, a circuit for energizing the busy relay R220 in the flat rate line circuit 200 individually associated with the telephone line 225. Further it is noted that the circuit for energizing the winding of the busy relay R220 is completed in the event the link 100 illustrated is the last available link in the first group of links, rendering all of the links in the first group of links busy at this time. In this event the circuit for energizing the winding of the busy relay R220 is completed and extends from ground by way of the chain conductor C643, the contacts 631, C231 and the winding of R220 to battery. When thus energized the busy relay R220 operates to interrupt, at the contacts 221, a point in the previously traced path for applying ground potential to the start conductor C230. Further it is noted that a path is normally completed for short-circuiting the winding 218 of the transformer 216 which extends from ground by way of the contacts 221 and the winding 213 of the transformer 216 to ground. Accordingly, upon operating the busy relay R220 interrupts, at the contacts 221, the above-traced path for short-circuiting the winding 218 of the transformer 216. Similarly the busy relay in each of the flat rate line circuits in the group of flat rate line circuits including the line circuit 200 is operated. Accordingly, when the next call is initiated at one of the subscriber substations in the group of subscriber substations, including the subscriber substation T1, the operation of the line and cut-off relay in the flat rate line circuit individually associated therewith will not cause ground potential to be applied to the start conductor C230 but will cause busy tone current to be returned to the receiver of the telephone instrument at the calling subscriber substation. By way of example, the analogous circuit for returning busy tone current over the telephone line 225 to the receiver of the telephone instrument at the subscriber substation T1 under these operating conditions extends from ground by way of the winding 218 of the transformer 216, the contacts 215 and 214, the condenser 219, the contacts 211, C226, the bridge path between the line conductors C226 and C227 of the telephone line 225 at the subscriber substation T1, C227, the contacts 212 and the lower winding of R210 to ground; the winding 217 of the transformer 216 being connected to a suitable source of busy tone current and being inductively coupled to the winding 218.

In connection with the extension of the call from the first B operator position 694 to a called telephone station in the local exchange 20 after the call has been answered at the first B operator position 694, it is noted by way of example, that the call may be extended to either

one of the subscriber substations T2 or T3 by inserting the calling plug of the cord circuit at the first B operator position 694 into the jack J202 terminating the telephone line 270 extending to the subscriber substations T2 and T3.

When the operator at the first A operator position 700 extends the call from her position to the first B operator position 694 she may wish to converse with the operator at the first B operator position 694 to the exclusion of the subscriber at the calling subscriber substation T1. In order to accomplish this result the operator at the first A operator position 700 operates the split key K775, thereby to complete, at the contacts 779 thereof, an obvious circuit for energizing the rear split relay R730 and to complete, at the contacts 776 and 777 thereof, an obvious connection between the impedance element I758 and the control conductors C746 and C747. Also when the split key K775 is operated an obvious connection is completed at the contacts 778 thereof between the line conductors C475 and C474 of the position trunk 470 including the condenser 746. When thus energized the rear split relay R730 operates to interrupt, at the contacts 731 and 733, the previously traced loop circuit extending between the calling subscriber substation T1 and the repeater 701 and to complete, at the contacts 732 and 734; an alternative loop circuit between the calling subscriber substation T1 and the impedance element I758. This alternative loop circuit extends from ground by way of the lower winding of the impedance element I758, the contacts 776 of the split key K775, C747 and the contacts 734 to the line conductor C475 of the position trunk 470, and from battery by way of the upper winding of the impedance element I758, the contacts 777 of the split key K775, C746, and the contacts 732 to the line conductor C474 of the position trunk 470; the line conductors C474 and C475 of the position trunk 470 being included in the previously traced loop circuit extending to the calling subscriber substation T1. With the split key K775 thus operated, the operator at the first A operator position 700 may converse with the operator at the first B operator position 694 to the exclusion of the subscriber at the calling subscriber substation T1. After the termination of the conversation between the operators at the first A operator position 700 and the first B operator position 694 the operator at the first A operator position 700 returns the split key K775 to its normal position, thereby to interrupt, at the contacts 779, the previously mentioned circuit for energizing the winding of the rear split relay R730; whereupon the rear split relay R730 restores to recomplete, at the contacts 731 and 733, the previously traced loop circuit between the calling subscriber substation T1 and the repeater 701. Also, at the contacts 776 and 777 of the split key K775, the impedance element I758 is disconnected from the control conductors C746 and C747.

In the event the operator at the first A operator position 700 should make an error in registering the digit to be transmitted to the selector switch 600 upon the key sender K720, the operated selector switch 600 may be restored to its normal position by operating the error release key K750 at the first A operator position 700. When the error release key K750 is thus operated an obvious circuit is completed, at the contacts 752 thereof, for energizing the wind-

ing of the front split relay R735, thereby to cause the latter relay to operate and complete, at the contacts 739, a path for applying ground potential to the line conductor C662 of the trunk 660;

- 5 660; this path extending from ground by way of the contacts 751 of the error release key K750, the contacts 744 and 739, the line conductor C472 of the position trunk 470, the contacts 464, the line conductor C483 of the feeder trunk 480, the contacts 454, C411, the contacts 556, C502, and the contacts L556 to the line conductor C662 of the trunk 660. This application of ground potential to the line conductor C662 of the trunk 660 completes an obvious path for short-circuiting in series the lower winding of the error relay R650 and the lower winding of the line relay R655. When the lower winding of the line relay R655 is thus short-circuited, this relay remains in its operated position; however, when the lower winding of the error relay R650 is thus short-circuited, this relay operates, as the error relay R650 is of the differential type. Upon operating, the error relay R650 completes, at the contacts 651, a circuit for energizing the winding of the lockout relay R625, this circuit extending from ground by way of the contacts 751 of the error release key K750, the resistor 785, the contacts 742 and 737, the line conductors C473 of the position trunk 470, the contacts 461, the line conductor C481 of the feeder trunk 480, the contacts 451, C410, the contacts 553, C501, the contacts L553, the line conductor C661 of the trunk 660, the contacts 651 and the winding of R625 to battery. When this circuit for energizing the winding of the lockout relay R625 is completed the latter relay does not operate due to the series resistance of this circuit, the lockout relay R625 being of the marginal type. Also the error relay R650 completes, at the contacts 653, an obvious alternative path for applying ground potential to the control conductor C663 of the trunk 660, thereby to retain the finder switch 300 in its operated position and to interrupt, at the contacts 654, the previously traced holding circuit for energizing the intermediate winding of the switching relay R670, thereby to cause the latter relay to restore. Finally the error relay R650 completes, at the contacts 652, a circuit for energizing the release magnet M618, this circuit extending from ground by way of the contacts 652, the release magnet M618 and the set of switch springs S619 to battery. When thus energized the release magnet M618 operates to release the wiper set of the mechanism 610 and to cause this wiper set to be returned to its normal position.
- 10 60 Accordingly, in order to release the operated selector switch 600 it is only necessary for the operator at the first A operator position 700 to operate the error release key K750 momentarily and then return it to its normal position. When the error release key K750 is returned to its normal position the previously mentioned circuit for energizing the winding of the front split relay R735 is interrupted, at the contacts 752 thereof, and the previously traced path for short-circuiting in series the lower winding of the error relay R650 and the lower winding of the line relay R655 is interrupted, at the contacts 751 thereof. Accordingly, the front split relay R735 then restores to recomplete, at the contacts 736 and 738, the previously traced loop circuit between the repeater 701 and the line relay R655 in the selector switch 600. Also the
- 15 70 75

error relay R650 restores in order to interrupt, at the contacts 652, a further point in the previously traced circuit for energizing the release magnet M618. At this time the selector switch 600 is completely released and is in condition to be responsive to impulses transmitted thereto from the key sender K720. Accordingly the operator at the first A operator position 700 again operates the key sender K720 in accordance with the proper digit, thereby to control the selector switch 600 in the manner previously explained.

After the call has been extended from the first A operator position 700 to the first B operator position 694 the operator at the first A operator position 700 causes the call to be transferred directly from the calling subscriber substation T1 to the first B operator position 694 by operating the transfer key K765. When the transfer key K765 is thus operated an obvious circuit is completed at the contacts 761 for energizing the magnet M747 of the peg count meter associated with the first A operator position 700, whereupon the peg count meter operates to register the extension of a call by the operator at the first A operator position 700. Also when the transfer key K765 is thus operated a path is completed, at the contacts 766 thereof, for short-circuiting the lower winding of the operated feeder relay in the operated switching unit in the first group of switching units; in the present example, a path is completed for short-circuiting the lower winding of the feeder relay R450 in the operated switching unit 400 in the first group of switching units, this path extending from ground by way of the contacts 766 of the transfer key K765, the control conductor C491 in the control trunk 490, the wiper 413 and engaged contact in the associated contact bank 414 of the sequence switch 410, C497, the contacts 458 and the lower winding of R450 to ground. Also, at the contacts 766 of the transfer key K765, an obvious alternative circuit is completed for energizing the winding of the operated start relay in the operated switching unit in the first group of switching units; in the present example, an alternative circuit is completed for energizing the winding of the operated start relay R430 in the operated first group of switching units. Accordingly, the feeder relay R450 restores, while the start relay R430 remains in its operated position at this time.

Upon restoring, the feeder relay R450 interrupts, at the contacts 458, the previously traced path for short-circuiting the lower winding thereof, interrupts, at the contacts 452 and 455, the previously traced loop circuit between the calling subscriber substation T1 and the repeater 701 at the first operator position 700, interrupts, at the contacts 451 and 454, the previously traced loop circuit between the repeater 701 at the first A operator position 700 and the line relay R655 in the selector switch 600, and completes, at the contacts 453 and 456, the previously traced direct loop circuit between the calling subscriber substation T1 and the line relay R655 in the selector switch 600. Further, the feeder relay R450 prepares, at the contacts 459, the previously traced multiple circuits for energizing the upper windings of the feeder relays in the first switching units in the various groups of switching units.

After the transfer key K765 is thus operated momentarily, it is returned to its normal posi-

tion to interrupt, at the contacts 761, the previously mentioned circuit for energizing the magnet M747 of the peg count meter associated with the first A operator position 700 and to interrupt, at the contacts 766, the previously mentioned alternative circuit for energizing the winding of the start relay R430, thereby to cause the latter relay to restore. Upon restoring, the start relay R430 interrupts, at the contacts 432, the previously traced connection between the control conductors C881 and C884 in the distributor trunk 880, thereby to interrupt a further point in the previously traced path for loading the battery associated with the resistor 812 in the A operator position distributor 830. Further, the start relay R430 interrupts, at the contacts 433, a further point in the previously traced path for applying ground potential to the control conductor C883 in the distributor trunk 880 and interrupts, at the contacts 434, the connection between the control conductors C882 and C880 in the distributor trunk 880, thereby to interrupt a further point in the previously mentioned chain circuit for energizing the winding of the busy relay R830 in the A operator position distributor 830. Further, the start relay R430 prepares, at the contacts 431, a further point in the previously traced multiple circuits for energizing the upper windings of the feeder relays in the first switching unit in the first group of switching units and interrupts, at the contacts 435, the previously traced series circuit for energizing the winding of the stop relay R440 and the winding of the start relay R770, thereby to cause the stop relay R440 to restore immediately and the start relay R770 to restore shortly thereafter, the latter relay being of the slow-to-release type. Finally, upon restoring, the start relay R430 completes, at the contacts 436, an alternative circuit for energizing the rotary magnet M419 of the sequence switch 410, this circuit extending from ground by way of the contacts 436, the wiper 411 and engaged contact in the associated contact bank 412 of the sequence switch 410, the contacts 420 and the winding of M419 to battery. When thus energized, the rotary magnet M419 operates to interrupt, at the contacts 420, the previously traced alternative circuit for energizing the rotary magnet M419, thereby to cause the rotary magnet M419 to restore and recomplete, at the contacts 420, the previously traced alternative circuit for energizing the rotary magnet M419. Accordingly, the rotary magnet M419 operates intermittently, thereby to drive the wipers noted of the sequence switch 410 step by step in the clockwise direction back into their normal positions, whereupon the wiper 411 disengages the last contact in the associated contact bank 412 having ground potential thereon, whereupon further operation of the rotary magnet M419 is arrested. At this time the sequence switch 410 in the first switching unit 400 in the first group of switching units is restored to its normal position.

When the sequence switch 410 is returned to its normal position the previously traced circuit for energizing the winding of the position relay R460 is interrupted at the wiper 417 and associated contact bank 418 of the sequence switch 410, thereby to cause the position relay R460 to restore. Upon restoring, the position relay R460 interrupts, at the contacts 461, 462, 464 and 465, the previously traced connections between the line conductors of the feeder trunk

480 and the line conductors of the position trunk 470.

Upon restoring, the start relay R770 interrupts, at the contacts RA771, a further point in the previously traced circuit for energizing the winding of the position relay R460 and interrupts, at the contacts RA772, the previously traced circuit for energizing in series the winding of the control relay R810 and the winding of the release relay R820 in the first call storage unit 800, thereby to cause the latter relays to restore. Also, the start relay R770 interrupts, at the contacts RA773, the previously mentioned path for applying ground potential to the control conductor C728, thereby to interrupt the previously traced multiple circuits for energizing the winding of the tone relay R725 and for illuminating the flat rate signal lamp L880, whereupon the tone relay R725 restores and the flat rate signal lamp L880 is extinguished. Finally, the start relay R770 interrupts, at the contacts 774, the previously mentioned connection between the control conductors C881 and C883 in the distributor trunk 880, thereby to interrupt the previously traced circuit prepared at the first A operator position 700 for energizing the left-hand winding of the position relay R860 in order to render the A operator position distributor 830 operative to select the first A operator position 700. At this time the first A operator position 700 is idle and is available to be selected by the first A operator position distributor 830.

At this time the direct loop circuit extending between the calling subscriber substation T1 and the line relay R655 is operatively connected by the condensers 628 and 629 to the loop circuit extending between the battery supply relay R630 in the selector switch 600 and the first B operator position 694. Accordingly, the subscriber at the calling subscriber substation T1 may converse with the operator at the first B operator position 694 and may ultimately converse with the called subscriber substation after the operator at the first B operator position has extended the connection to the called subscriber substation in 45 the local exchange 20.

Recall of an A operator position from a B operator position

After the connection from the calling subscriber substation T1 has been transferred from the first A operator position 700 directly by way of the link 100 illustrated to the first B operator position 694, the operator at the first B operator position 694 may have occasion to recall an A operator position. An idle A operator position may be recalled, over the established connection between the calling subscriber substation T1 and the first B operator position 694 including the link 100 illustrated, under the control of the operator at the first B operator position 694. In order to accomplish this end the operator at the first B operator position 694 operates the apparatus at her position, thereby to cause the loop circuit extending between the battery supply relay R630 in the selector switch 600 and the first B operator position 694 to be momentarily interrupted and then recompleted, thus causing the battery supply relay R630 instantaneously to restore and then reoperate. Upon restoring, the battery supply relay R630 interrupts, at the contacts 633, the previously mentioned circuit for energizing the winding of the control relay R640 and completes, at the contacts 634, an obvious circuit for energizing the

lower winding of the call back relay R645. The control relay R640, being of the slow-to-operate type, is also slightly slow to release. Accordingly, the control relay R640 does not immediately restore, and when the battery supply relay R630 reoperates, it recompletes, at the contacts 633, the previously mentioned circuit for energizing the winding of the control relay R640. When the previously mentioned circuit for energizing the lower winding of the call back relay R645 is completed, the latter relay operates to complete, at the contacts 646, a holding circuit for energizing the upper winding thereof in series with the winding of the feeder relay in the first switching unit in a prepared one of the groups of switching units, one of the groups of switching units being prepared at this time under the control of the A operator position distributor 830 in the manner previously explained. More particularly, at this time, in the event the A operator position distributor 830 has operated to select the first group of switching units and the corresponding first A operator position 100, battery potential appears upon the control conductor C884 in the distributor trunk 880; on the other hand, in the event the A operator position distributor 830 has selected the second group of switching units and the corresponding second A operator position, battery potential appears upon the control conductor C888 in the distributor trunk 880; etc. In the event battery potential appears upon the control conductor C884 in the distributor 880, a circuit is completed for energizing in series the upper winding of the call back relay R645 and the upper winding of the feeder relay R550 in the first switching unit 500 in the second group of switching units; etc.

Assuming that the A operator position distributor 830 has operated to select the first switching unit 400 in the first group of switching units and the corresponding first A operator position 700 at this time, battery potential appears upon the control conductor C884 in the distributor trunk 880, whereupon a circuit is completed for energizing in series the upper winding of the call back relay R645 and the upper winding of the feeder relay R450 in the first switching unit 400 in the first group of switching units, this circuit extending from ground by way of the upper winding of R645, the contacts 646 and 632, the control conductor C664 of the trunk 660, the contacts L559, 559 and 459, the upper winding of R450 and the contacts 431 to the control conductor C884 in the distributor trunk 880 having battery potential thereon. When thus energized, the feeder relay R450 operates to complete, at the contacts 458, the previously traced series circuit for energizing the lower winding thereof and the winding of the start relay R430 and interrupts, at the contacts 459, the previously traced prepared multiple circuits for energizing in series the upper winding of the call back relay R645 and the upper windings of the feeder relays in the first switching units in the other groups of switching units. Also, the feeder relay R450 interrupts, at the contacts 459, the previously traced circuit for energizing the upper winding of the call back relay R645 in series with

the upper winding of the feeder relay R450, thereby to cause the call back relay R645 to restore shortly thereafter, the latter relay being of the slow-to-release type.

Upon operating, the feeder relay R450 and the start relay R430 cause operation of the sequence switch 410, the position relay R460 and the start relay R770 in the manner previously explained, whereupon the recall upon the established connection between the calling subscriber substation T1 and the operator at the first B operator position 694 is routed to the first A operator position 700 to be answered. At this time, when the feeder relay R450 and the position relay R460 are operated, the previously traced direct loop circuit between the calling subscriber substation T1 and the line relay R655 in the selector switch 600 is interrupted; the previously traced loop circuit between the calling subscriber substation T1 and the repeater 701 at the first A operator position 700 is recompleted; and the previously traced loop circuit between the line relay R655 in the selector switch 600 and the repeater 701 at the first A operator position 700 is recompleted. Accordingly, at this time, a three-way communication connection is completed which includes the calling subscriber substation T1, the first B operator position 694 and the first A operator position 700. Accordingly, at this time, the operator at the first A operator position 700 may converse with either the subscriber at the calling subscriber substation T1 or the operator at the first B operator position 694. Hence, it will be understood that in the event the subscriber at the calling subscriber substation T1 desires another connection, the operator at the first A operator position 700 may release the selector switch 600 by operating the error release key K750 at her position and subsequently reoperate the selector switch 600 by operating the key sender K730 at her position, thereby to establish another connection between the calling subscriber substation T1 and any desired called operator position.

Release of an established connection between a calling subscriber substation and a called operator position

The release of an established connection between a calling subscriber substation, such, for example, as the calling subscriber substation T1 and a called operator position, such, for example, as the first B operator position 694 routed therebetween by way of the link 100 illustrated, is primarily under the control of the operator at the first B operator position 694. It is noted that the operator at the first B operator position 694 releases the connection from her position to the called subscriber substation in the local exchange 20 by operating the apparatus at her position, in the usual manner, and initiates the release of the established connection between her position and the selector switch 600 by interrupting the loop circuit between the battery supply relay R630 in the selector switch 600 and the first B operator position 694, thereby to cause the battery supply relay R630 to restore. Upon restoring the battery supply relay R630 interrupts, at the contacts 633, the previously mentioned circuit for energizing the winding of the control relay R640, thereby to cause the latter relay to restore. Upon restoring the control relay R640 interrupts, at the contacts 641, the previously traced path for applying ground potential to the control conductor C663 of the trunk 660, thereby to inter-

rupt the previously traced holding circuit for energizing the intermediate winding of the switching relay R670. The switching relay R670 then restores to prepare, at the contacts 675, the previously mentioned circuit for energizing the release magnet M618.

Also when ground potential is removed from the control conductor C663 of the trunk 660 the previously traced holding circuit for energizing 10 the intermediate winding of the switching relay R320 in the finder switch 300 is interrupted, thereby to cause the latter relay to restore. Upon restoring, the switching relay R320 completes, at the contacts 321, the previously mentioned circuit 15 for energizing the release magnet M369, this circuit extending from ground by way of the contacts 321, 331 and 341, the set of switch springs S370 and M369 to battery. When thus energized the release magnet M369 operates to release the first and second wiper sets of the mechanism 310 20 and to cause these wiper sets to be returned to their normal positions, whereupon the sets of switch springs S370, S371 and S372 are actuated. More particularly, the set of switch springs S370 is actuated into disengagement, thereby to interrupt the previously traced circuit for energizing the release magnet M369 in order to cause the release magnet M369 to restore. The set of switch springs S372 is actuated into engagement, 25 thereby to complete the previously traced path for applying ground potential to the all-link-busy conductor C309. Finally the contacts 372 of the set of switch springs S371 are actuated into disengagement, thereby to interrupt the previously traced path for applying ground potential to the guard conductor C303. At this time the finder switch 300 is completely released.

When the finder switch 300 is released the previously traced loop circuit between the calling subscriber substation T1 and the line relay R655 in the selector switch 600 is interrupted, thereby to cause the latter relay to restore. Upon restoring the line relay R655 completes, at the contacts 657, the previously mentioned circuit for energizing the release magnet M618, this circuit extending from ground by way of the contacts 675, 45 657, 660 and 669, M618 and the set of switch springs S619 to battery. When thus energized the release magnet M618 operates to release the wiper set of the mechanism 610 and to cause this wiper set to be returned to its normal position, 50 whereupon the sets of switch springs S619, S620 and S621 are actuated. More particularly the set of switch springs S619 is actuated into disengagement, thereby to interrupt the previously traced circuit for energizing the release magnet M618, thereby to cause the release magnet M618 to restore. The set of switch springs S621 is actuated into disengagement, thereby to interrupt a further point in the previously traced 55 circuit for energizing the rotary magnet M616; and the set of switch springs S620 is actuated into engagement, thereby to prepare the previously traced circuit for energizing the upper winding of the transfer relay R665. At this time the selector switch 600 is completely released.

When the selector switch 600 is released the previously traced circuit for energizing the winding of the line relay R680 in the trunk line circuit 680 individually associated with the trunk 690 extending to the first B operator position 694 is interrupted, thereby to cause the line relay R680 to restore. Upon restoring the line relay R680 prepares, at the contacts 681, the previously traced circuit for energizing the winding

of the busy relay R685. At this time the trunk line circuit 680 is completely released and battery potential is applied by way of the winding of the line relay R680 to the control conductor C693 of the trunk 690, thereby to mark the trunk 690 as idle. Accordingly at this time, the apparatus at the first B operator position 694 utilized in the established connection between the calling subscriber substation T1 and the first B operator position 694 is completely released.

Assuming that the subscriber at the calling subscriber substation T1 has replaced the receiver of the telephone instrument thereat upon its switchhook, when the finder switch 300 is released the previously traced circuit for energizing the intermediate winding of the line and cutoff relay R210 in the flat rate line circuit 200 individually associated with the telephone line 225 extending to the subscriber substation T1 is interrupted, thereby to cause the line and cutoff relay R210 to restore. At this time battery potential is applied by way of the intermediate winding of the line and cutoff relay R210 to the control conductor C229 of the telephone line 225, thereby to mark the telephone line 225 extending to the subscriber substation T1 as idle. At this time the flat rate line circuit 200 individually associated with the telephone line 225 extending to the subscriber substation T1 is completely released.

Party subscriber substation call

A call from a party subscriber substation, such, for example, as the party subscriber substation T2, is initiated by removing the receiver of the telephone instrument thereat from its switchhook. When the receiver of the telephone instrument at the subscriber substation T2 is removed from its switchhook, a bridge path is completed between the line conductors C271 and C272 of the telephone line 270 extending to the subscriber substation T2. When this bridge path is completed between the line conductors of the telephone line 270 a circuit is completed for energizing in series the windings of the line and cutoff relay R260. This circuit extends from ground by way of the lower winding of R260, the contacts 262, 254 and 249 to C272, the bridge path between the line conductors C272 and C271, C271, the contacts 246, 251 and 261 and the upper and intermediate windings of R260 to battery. When thus energized over the abovetraced circuit the line and cutoff relay R260 operates partially, thereby to complete, at the contacts 264, an obvious path for applying ground potential to the start conductor C266 and to complete, at the contacts 263, an obvious connection between the control conductors C275 and C273 of the telephone line 270. The application of ground potential to the start conductor C266 completes an obvious path for applying ground potential by way of the resistor 303 of the marking network 305 to the start conductor C308 extending to the distributor 301 and an obvious path for applying direct ground potential to the second contacts in the vertical control contact banks of the finder switches having access thereto. The application of ground potential to the start conductor C308 initiates operation of the distributor 301 and the application of direct ground potential to the second contacts in the vertical control contact banks of the finder switches mentioned marks the telephone line 270 as terminating in the second level of the main contact banks of these finder switches.

The finder distributor 301 then operates to cause 75

the previously selected link in the first group of links to be assigned to the use of the calling subscriber substation T2 in the previously described manner. Assuming that the distributor 301 operates to assign the link 100 illustrated in the first group of links to the use of the calling subscriber substation T2, the finder switch 300 operates, in the previously described manner, to seize the telephone line 270 extending to the calling subscriber substation T2. Also the selector switch 600 and the first switching unit 400 in the first group of switching units operate in the manners previously described, assuming that the A operator position distributor 830 has previously selected the first group of switching units and the corresponding first A operator position 700. In this event, the first switching unit 400 in the first group of switching units operates in order to complete a loop circuit substantially identical to that previously traced between the calling subscriber substation T2 and the repeater 701 at the first A operator position 700 and to complete the previously traced loop circuit between the line relay R655 in the selector switch 600 and the repeater 701 at the first A operator position 700, the operation of the first switching unit 400 including the sequence switch 410 being the same as that previously explained.

At this point it is noted that the operation of the finder switch 300 to seize the telephone line 270 is only slightly different from the operation thereof to seize the telephone line 225; the difference in the operation of the finder switch 300 residing in the fact that the telephone line 225 is terminated by the first section of the main contact bank associated with the first wiper set of the mechanism 310, while the telephone line 270 is terminated by the second section of the main contact bank associated with the second wiper set of the mechanism 310. Accordingly, during the operation of the finder switch 300 at this time, when the second wiper set engages the contact set in the second section of the main contact bank of the mechanism 310 terminating the telephone line 270 a circuit is completed for energizing the upper winding of the switching relay R330, this circuit extending from ground by way of the contacts 342, the upper winding of R330, the contacts 326, the wiper 316, the control conductor C275 of the telephone line 270, the contacts 263 and the intermediate winding of R260 to battery. When thus energized the switching relay R330 operates to complete, at the contacts 338, a holding circuit for energizing the intermediate winding thereof, this circuit extending from ground by way of the contacts 342 and 338 and the intermediate winding of R330 to battery. Further the switching relay R330 interrupts, at the contacts 336, a further point in the previously traced holding circuit for energizing the intermediate winding of the switching relay R320, thereby positively to prevent the latter relay from being retained in its operated position at this time in the event it is operated. Further the switching relay R330 interrupts, at the contacts 330, the previously traced circuit for energizing the rotary magnet M367, thereby positively to arrest further operation of the rotary magnet M367 at this time. Also the switching relay R330 completes, at the contacts 337, a low resistance circuit for energizing the intermediate winding of the line and cutoff relay R260, this circuit extending from ground by way of the contacts 342 and 337, the wiper 316, the control conductor C275 of the telephone line 270, the contacts 263

and the intermediate winding of R260 to battery. When thus energized the line and cutoff relay R260 operates completely, thereby to interrupt, at the contacts 265, the previously mentioned path for applying ground potential to the start conductor C266 in order to arrest further operation of the distributor 301. Also the line and cutoff relay R260 interrupts, at the contacts 261 and 262, the previously traced circuit for energizing the windings thereof across the line conductors C271 and C272 of the telephone line 270, thereby to clear the telephone line 270 of impedance elements.

Finally the switching relay R330 completes, at the contacts 333 and 335, a loop circuit between the calling subscriber substation T2 and the repeater 701 at the first A operator position 700. This loop circuit extends from the line conductor C271 of the telephone line 270 by way of the contacts 246 and 251, C277, the wiper 314 and the contacts 333 to the line conductor C361 of the trunk 360, and from the line conductor C272 of the telephone line 270 by way of the contacts 249 and 254, C274, the wiper 315 and the contacts 335 to the line conductor C362 of the trunk 360, the receiver of the telephone instrument at the calling subscriber substation T2 being connected across the line conductors C271 and C272 of the telephone line 270, and the line conductors C361 and C362 of the trunk 360 being connected by way of the line conductors of the feeder trunk 480 and the line conductors of the position trunk 470 to the repeater 701 at the first A operator position 700 as previously traced.

Further, it is noted that when the feeder relay R450 and the position relay R460 operate they complete, at the contacts 451 and 461, respectively, a circuit for energizing in series the winding of the control relay R245 in the two-party line register circuit 240 individually associated with the telephone line 270 extending to the calling subscriber substation T2 and the windings of the signal relays R885 and R890. This circuit extends from ground by way of the resistor 244, the winding of R245, the control conductor C276 of the telephone line 270, the wiper 317, the control conductor C364 of the trunk 360, the contacts 451, the control conductor C485 of the feeder trunk 480, the contacts 461, the control conductor C471 of the position trunk 470, the contacts 762 of the control key K760, C738, the contacts 792 of the second register key K790, the contacts 797 of the first register key K795, C729, R885 and R890 to battery. When this series circuit is completed the signal relay R885 operates; however, the control relay R245 and the signal relay R890 do not operate due to the high series resistance of this circuit. Upon operating, the signal relay R885 completes, at the contacts 887, a circuit for illuminating the message register lamp L881, this circuit extending from ground by way of the contacts RA713, 881 and 891 and the signal lamp L881 to battery. The illumination of the message register signal lamp L881 indicates to the operator at the first A operator position 700 that the calling subscriber substation is rendered message register service. Accordingly, when the operator at the first A operator position answers the call she requests the subscriber at the calling subscriber substation to identify his subscriber substation. In the present instance, the calling subscriber substation T2 corresponds to the second message register in the two-party line register circuit 240. Accordingly the operator at the first A operator position subsequently operates the second regis-

ter key K790 in order to operate the second register in the two-party line register circuit 240. When the second register key K790 is operated an obvious circuit is completed at the contacts 194 thereof for energizing the rear split relay R730, thereby to cause the latter relay to operate and complete, at the contacts 732 and 734, a connection between the line conductors C474 and C475 of the position trunk 470 and the control conductors C146 and C147. Also when the second register key K790 is operated the previously traced series circuit for energizing the winding of the control relay R245 and the windings of the signal relays R885 and R890 is interrupted at the contacts 792 thereof. Also, at the contacts 791 of the second register key K790, a circuit is completed for energizing the winding of the control relay R245, this circuit extending from ground by way of the resistor 244, R245, the control conductor C276 of the telephone line 270 and the wiper 317 to the control conductor C364 of the trunk 360 and therefrom by way of the control conductor C485 of the feeder trunk 480 to the control conductor C471 of the position trunk 470 and therefrom by way of the contacts 162 of the control key K760, C738, the contacts 791 of the second register key K790 and the resistor 764 to battery. When thus energized the control relay R245 operates, thereby to complete, at the contacts 247 and 248, obvious connections between the second and first register magnets M241 and M242, respectively, and the line conductors C277 and C274, respectively, of the telephone line 270. Finally when the second register key K790 is operated there is completed, at the contacts 793, a circuit for energizing the second register magnet M241, this circuit extending from ground by way of the second register magnet M241, the contacts 247 and 251, the line conductor C277 of the telephone line 270, the wiper 314 and the contacts 333 to the line conductor C361 of the trunk 360, and therefrom by way of the line conductor C482 of the feeder trunk 480 to the line conductor C474 of the position trunk 470, and therefrom by way of the contacts 732, C146, the contacts 793 of the second register key K790 and the resistor 764 to battery. When thus energized the second register magnet M241 operates in order to cause the second register to register a call at the calling subscriber substation T2.

After the second register key K790 is thus operated it is returned to its normal position, whereupon the previously traced circuit for energizing the winding of the rear split relay R730 is interrupted at the contacts 794 thereof and the previously traced circuit for energizing the winding of the control relay R245 is interrupted at the contacts 791 thereof, thereby to cause the control relay R245 and the rear split relay R730 to restore. Also, at the contacts 793 of the second register key K790, a further point in the previously traced circuit for energizing the second register magnet M241 is interrupted and, at the contacts 792, the previously traced series circuit for energizing the winding of the control relay R245 and the windings of the signal relays R885 and R890 is recompleted.

The extension of the call from the first A operator position 700 to one of the called operator positions, such, for example, as the first B operator position 694, and the subsequent completion of a direct connection between the calling subscriber substation T2 and the first B operator position 694 are the same as those pre-

viously explained. Also the release of the established connection between the calling subscriber substation T2 and the first B operator position 694 is the same as that previously explained.

From the foregoing explanation of the extension of a call from the calling subscriber substation T2 to an idle A operator position, such, for example, as the first A operator position 700, it will be understood that a call from the subscriber substation T3 is extended to the first A operator position 700 in precisely the same manner as the extension of the call from the calling subscriber substation T2 to the first A operator position 700. However, it is noted that after the operator at the first A operator position 700 answers the call and communicates with the subscriber at the calling subscriber substation T3 the first register key K795, instead of the second register key K790, is operated, thereby to cause the first register in the two-party line circuit 240 corresponding to the calling subscriber substation T3 to be operated.

More particularly, at this time when the first register key K795 is operated there is completed, at the contacts 799 thereof, an obvious circuit for energizing the winding of the rear split relay R730, thereby to cause the latter relay to operate. Also, at the contacts 796 of the first register key K795, there is completed a circuit substantially identical to that previously traced for energizing the winding of the control relay R245, thereby to cause the latter relay to operate. Further, at the contacts 797 of the first register key K795, the previously traced series circuit for energizing the winding of the control relay R245 and the windings of the signal relays R885 and R890 is interrupted. Finally, at the contacts 798 of the first register key K795, a circuit is completed for energizing the first register magnet M242, this circuit extending from ground by way of the first register magnet M242, the contacts 248 and 254, the line conductor C274 of the telephone line 270, the wiper 315 and the contacts 335 to the line conductor C362 of the trunk 360, and therefrom by way of the line conductor C484 of the feeder trunk 480 to the line conductor C475 of the position trunk 470, and therefrom by way of the contacts 734, C747, the contacts 798 of the first register key K795 and the resistor 764 to battery. When thus energized the first register magnet M242 operates to cause the first register corresponding to the subscriber substation T3 to operate, thereby to register the call at the subscriber substation T3.

When the first register key K795 is restored to its normal position the previously traced circuits for energizing the winding of the control relay R245 and the first register magnet M242 are respectively interrupted, at the contacts 796 and 798 thereof. Also, at the contacts 799 of the first register key K795, the previously mentioned circuit for energizing the winding of the rear split relay R730 is interrupted. Finally, at the contacts 797 of the first register key K795, the previously traced series circuit for energizing the winding of the control relay R245 and the windings of the signal relays R885 and R890 is recompleted. Accordingly, at this time the first register magnet M242, the control relay R245 and the rear split relay R730 restore, while the signal relay R885 re-operates.

What has been said with reference to the extension of the call from the first A operator position 700 to one of the called operator positions

and the subsequent release of the established connection between the calling subscriber substation and the called operator position applies directly to the call initiated at the calling subscriber substation T3.

Reverting call between party subscriber sub-stations

A reverting call which is to be extended from one party subscriber substation, such, for example, as the party subscriber substation T2, to another party subscriber substation T3 on the same telephone line 270 is first initiated at the calling subscriber substation T2 and extended to one of the A operator positions, in the manner previously explained. Assuming that the call is extended from the calling subscriber substation T2 by way of the link 100 illustrated to the first A operator position 700, the operator at the first A operator position 700 first answers the call and is advised by the subscriber at the subscriber substation T2 that the call is to be extended to the called subscriber substation T3 on the same telephone line 270. The operator at the first A operator position 700 then advises the subscriber at the calling subscriber substation T2 to replace the receiver of the telephone instrument thereat upon its switchhook and then operates the reverting call key K770, thereby to complete, at the contacts 773 thereof, an obvious circuit for energizing the winding of the rear split relay R730 and to complete, at the contacts 771 and 772 thereof, a circuit for projecting ringing current over the telephone line 270 upon operation of the rear split relay R730. This circuit extends from one terminal of a source of ringing current, not shown, by way of the conductor C741, the contacts 772 of the reverting call key K770, C747 and the contacts 734 to the line conductor C475 of the position trunk 470, and therefrom by way of the previously traced path to the line conductor C272 of the telephone line 270 and from the other terminal of the source of ringing current, not shown, by way of the conductor C742, the contacts 771 of the reverting call key K770, C746 and the contacts 732 to the line conductor C474 of the position trunk 470, and therefrom by way of the previously traced path to the line conductor C271 of the telephone line 270, the ringers at the subscriber substations T2 and T3 being connected across the line conductors of the telephone line 270. Accordingly the ringers at the subscriber substations T2 and T3 are operated at this time.

At this point it is noted that code ringing may be utilized and that a code selector switch may be interposed between the source of ringing current and the line 740 extending thereto, whereby different codes of ringing current may be transmitted over the telephone line 270 in order selectively to control the operation of the ringers at the subscriber substations T2 and T3. Further it is noted that while the telephone line 270 is being rung over the finder switch 300 the selector switch 600 is retained in its operated position due to the completed loop circuit between the line relay R655 in the selector switch 600 and the retarder coil 730 connected across the line conductors C472 and C473 of the position trunk 470 at this time.

After operating the reverting call key K770 in order to cause ringing current to be projected over the telephone line 270, the operator at the first A operator position 700 restores the reverting call key K770 to its normal position, thereby

to interrupt, at the contacts 773 thereof, the previously mentioned circuit for energizing the winding of the rear split relay R730 and to interrupt, at the contacts 771 and 772 thereof, the previously traced circuit for projecting ringing current over the telephone line 270. The rear split relay R730 then restores, thereby to recomplete, at the contacts 731 and 733, the previously traced loop circuit between the repeater 701 and the calling subscriber substation T2, assuming that the subscriber at the calling subscriber substation T2 has removed the receiver of the telephone instrument thereat from its switchhook at this time. Further assuming that the subscriber at the called subscriber substation T3 has answered the call by removing the receiver of the telephone instrument thereat from its switchhook at this time, an established connection is completed between the calling subscriber substation T2 and the called subscriber substation T3. Also the connection between the telephone line 270 and the first A operator position 700 is recompleted at this time. Accordingly, the operator at the first A operator position 700 may converse with the subscribers at the subscriber substations T2 and T3 advising them to proceed with the conversation.

The operator at the first A operator position 700 then operates the permanent lockout release key K755, thereby to complete, at the contacts 757 thereof, an obvious circuit for energizing the winding of the front split relay R735 and to complete, at the contacts 756 thereof, a path for connecting ground potential to the line conductor C661 of the trunk 660 upon operation of the front split relay R735. Upon operating the front split relay R735 interrupts, at the contacts 736 and 738, the previously traced loop circuit extending between the line relay R655 in the selector switch 600 and the repeater 701. However, at this time, an alternative circuit is completed for energizing in series the upper winding of the error relay R650 and the upper winding of the line relay R655, this circuit extending from ground by way of the contacts 756 of the permanent lockout release key K755, the contacts 742 and 737, the line conductor C473 of the position trunk 470, the contacts 461, the line conductor C481 of the feeder trunk 480, the contacts 451, C410, the contacts 553, C501, the contacts L553, the line conductor C661 of the trunk 660, the upper winding of R650 and the upper winding of R655 to battery. Accordingly the line relay R655 remains in its operated position; while the error relay R650 operates, the lower winding thereof being short-circuited at this time. Upon operating the error relay R650 completes, at the contacts 651, a circuit for energizing the winding of the lockout relay R625, this circuit extending from direct ground by way of the contacts 756 of the permanent lockout release key K755 over the previously traced path to the line conductor C661 of the trunk 660 and therefrom by way of the contacts 651 and the winding of R625 to battery. When thus energized the lockout relay R625 operates to interrupt, at the contacts 627, the previously traced path for applying ground potential to the control conductor C663 of the trunk 660 and to complete, at the contacts 626, a path for applying booster battery potential to the control conductor C663 of the trunk 660. The path for applying booster battery potential to the control conductor C663 of the trunk 660 extends from ground by way of the booster battery 624 and the contacts 626 to the control conductor C663. 75

This application of booster battery potential to the control conductor C663 of the trunk 660 completes an alternative holding circuit substantially identical to that previously traced for energizing the intermediate winding of the switching relay R320 and completes a circuit for effectively energizing the lockout relay R250 in the two-party line register circuit 240 individually associated with the telephone line 270. The circuit for energizing the winding of the lockout relay R250 extends from booster battery potential appearing on the control conductor C663 of the trunk 660 by way of the control conductor C363 of the trunk 360, the contacts 337, the wiper 316, the control conductor C275 of the telephone line 270, the contacts 263, the resistor 258 and the winding of R250 to battery. When thus energized the lockout relay R250 operates to complete, at the contacts 252 and 253, a holding circuit for energizing the winding thereof, this circuit extending from ground by way of the contacts 252 and 246, C271, the bridge paths at the subscriber substations T2 and T3 between the line conductors C271 and C272 of the telephone line 270, C272, the contacts 249 and 253 and the winding of R250 to battery. Also the lockout relay R250 completes, at the contacts 255, an obvious path for applying ground potential to the control conductor C273 of the telephone line 270, thereby to mark the telephone line 270 as busy to the B operator positions having access thereto. Further the lockout relay R250 completes, at the contacts 257, an obvious circuit for illuminating the permanent signal lamp L243. The illumination of the permanent signal lamp L243 indicates to the operators at the A operator positions that the telephone line 270 is locked out of service at this time. Finally the lockout relay R250 interrupts, at the contacts 251 and 254, the previously traced loop circuit between the subscriber substations T2 and T3 and the repeater 701.

After the permanent signal lamp L243 is illuminated, in order to indicate to the operator at the first A operator position 700 that the telephone line 270 is locked out of service the operator at the first A operator position 700 restores the permanent lockout release key K755 to its normal position, thereby to interrupt, at the contacts 757 thereof, the previously mentioned circuit for energizing the winding of the front split relay R735 and to interrupt, at the contacts 756 thereof, the previously traced loop circuit for energizing in series the upper winding of the error relay R650 and the upper winding of the line relay R655. Accordingly the front split relay R735 restores to recomplete, at the contacts 736 and 738, the previously traced loop circuit between the line relay R655 in the selector switch 600 and the repeater 701, thereby to cause the error relay R650 to restore. Upon restoring the error relay R650 interrupts, at the contacts 651, the previously traced circuit for energizing the winding of the lockout relay R625, thereby to cause the latter relay to restore. Upon restoring the lockout relay R625 interrupts, at the contacts 626, the previously traced path for applying booster battery potential to the control conductor C663 of the trunk 660 and completes, at the contacts 627, the previously traced path for applying ground potential to the control conductor C663 of the trunk 660. Accordingly at this time, only the loop circuit extending between the line relay R655 in the selector switch 600 and the repeater 701 is completed.

The operator at the first A operator position

700 then momentarily operates the transfer key K765 and then returns this key to its normal position. When the transfer key K765 is thus momentarily operated, the previously traced path for short-circuiting the lower winding of the feeder relay R450 in the first switching unit 400 in the first group of switching units is completed, thereby to cause the feeder relay R450, the position relay R460 and the start relay R770 to be restored and the sequence switch 410 to be operated back to its normal position as previously explained. Upon restoring, the feeder relay R450 interrupts, at the contacts 451 and 454, the previously traced loop circuit extending between the line relay R655 in the selector switch 600 and the repeater 701 at the first A operator position 700, thereby to cause the line relay R655 to restore. The restoration of the line relay R655 effects the release of the finder switch 300 and the selector switch 600 in the manner previously explained. Accordingly, at this time, the link 100 illustrated and the first A operator position 700 are completely released, while the telephone line 270 is locked out of service.

When the subscribers at the subscriber substations T2 and T3 replace the receivers of the respective telephone instruments thereat upon their switchhooks the bridge paths between the line conductors C271 and C272 of the telephone line 270 are interrupted, thereby to interrupt the previously traced holding circuit for energizing the winding of the lockout relay R250. The lockout relay R250 then restores, thereby to cause the two-party line register circuit 240 to place the telephone line 270 again in service. Further the lockout relay R250 interrupts, at the contacts 257, the previously mentioned circuit for illuminating the permanent signal lamp L243, thereby to cause the signal lamp L243 to be extinguished in order to indicate to the operators at the A operator positions that the telephone line 270 is no longer locked out of service. Finally the lockout relay R250 interrupts, at the contacts 255, the previously mentioned path for applying ground potential to the control conductor C273 of the telephone line 270 and completes, at the contacts 256, the previously traced path for applying battery potential by way of the intermediate winding of the line and cutoff relay R260 to the control conductor C273 of the telephone line 270, thereby to mark the telephone line 270 as idle.

In connection with the operation of the two-party line register circuit 240 it is noted that in the event a permanent fault appears upon the telephone line 270 the two-party line register circuit 240 operates in order to create a call upon the telephone line 270 in the manner previously described, thereby to initiate operation of the distributor 301. The distributor 301 then assigns a previously selected link in the first group of links to the use of the calling telephone line 270, such, for example, as the link 100 illustrated, whereupon the finder switch 300 operates to seize the telephone line 270 in the manner previously explained. Also the first switching unit in one of the groups of switching units, such, for example, as the first switching unit 400 in the first group of switching units, operates, thereby to extend the call to the first A operator position 700 in order to cause the call to be routed by the finder switch 300 to the first A operator position 700. When the operator at the first A operator position 700 challenges

the line 270 and is unable to communicate with either the subscriber at the subscriber substation T2 or the subscriber at the subscriber substation T3, she concludes that a permanent fault is present on the telephone line 270. The operator at the first A operator position 700 then proceeds to cause the two-party line register circuit 240 to operate in order to lock the telephone line 270 out of service by operating the permanent lockout release key K755, in the manner previously explained. The operator at the first A operator position 700 then operates the transfer key K765 in order to cause the finder switch 300, the selector switch 600 and the first A operator position 700 to be released, as previously explained. At this time the line 270 remains locked out of service until the fault thereon is removed, thereby to cause the previously traced holding circuit for energizing the winding of the lockout relay R250 to be interrupted. The lockout relay R250 then restores, thereby again to place the telephone line 270 in service, in the manner previously explained.

Paystation call

25 A call from a paystation, such, for example, as the paystation T4, is initiated by removing the receiver of the telephone instrument thereat from its switchhook and depositing a coin in the coin slot of the telephone instrument thereat. When the receiver of the telephone instrument at the paystation T4 is removed from its switchhook and the coin is deposited in the coin slot of the telephone instrument thereat, a bridge path is completed between the line conductors C285 and C287 of the telephone line 285 extending to the paystation T4 and the prepay manual line circuit 280 individually associated with the telephone line 285 is operated in order to cause battery potential to be applied to the control conductor C288 of the telephone line 285, to cause direct ground potential to be applied to the control conductor C289 of the telephone line 285 and to cause ground potential to be applied to the start conductor C291. The application of ground potential to the start conductor C291 completes an obvious path for applying ground potential by way of the resistor 302 of the marking network 305 to the start conductor C308 extending to the distributor 301, and an obvious path for applying direct ground potential to the third contacts in the vertical control contact banks of the finder switches having access thereto. The application of ground potential to the start conductor C308 initiates operation of the distributor 301 and the application of direct ground potential to the third contacts in the vertical control contact banks of the finder switches mentioned marks the telephone line 285 as terminating in the third level of the main contact banks of these finder switches.

65 The finder distributor 301 then operates to cause the previously selected link in the first group of links to be assigned to the use of the calling paystation T4, in the previously described manner. Assuming that the distributor 301 operates to assign the link 100 illustrated in the first group of links to the use of the calling paystation T4, the finder switch 300 operates in the manner previously described to seize the telephone line 285 extending to the calling paystation T4. Also the selector switch 600 and the first switching unit 400 in the first group of switching units operate in the manners previously described, assuming that the A operator

position distributor 830 has previously selected the first group of switching units and the corresponding first A operator position 700. In this event, the first switching unit 400 in the first group of switching units operates in order to complete a loop circuit substantially identical to that previously traced between the calling paystation T4 and the repeater 701 at the first A operator position 700 and to complete the previously traced loop circuit between the line relay R655 in the selector switch 600 and the repeater 701 at the first A operator position 700, the operation of the first switching unit 400 including the sequence switch 410 being the same as that previously explained.

At this point it is noted that the operation of the finder switch 300 to seize the telephone line 285 is the same as the operation thereof to seize the telephone line 270 previously described. The loop circuit extending between the calling paystation T4 and the repeater 701 at the first A operator position 700 extends from the line conductor C286 of the telephone line 285 by way of the wiper 314 and the contacts 333 to the line conductor C361 of the trunk 360 and therefrom by way of the previously traced circuit including the repeater 701 at the first A operator position 700 to the line conductor C362 of the trunk 360 and therefrom by way of the contacts 335 and the wiper 315 to the line conductor C287 of the telephone line 285, the line conductors C286 and C287 of the telephone line 285 being connected together by way of the bridge path at the calling paystation T4.

Also, when the finder switch 300 seizes the telephone line 285 direct ground potential is applied by way of the wiper 316 to the control conductor C288 of the telephone line 285, thereby to cause the prepay manual line circuit 280 individually associated with the telephone line 285 to operate and free the line conductors C286 and C287 of the telephone line 285 of impedance elements. Also the prepay manual line circuit 280 operates to interconnect the control conductors C288 and C290 of the telephone line 285, thereby to cause ground potential to be applied to the control conductor C290 of the telephone line 285 in order to mark the telephone line 285 as busy to the B operator positions having access thereto.

Upon operating, the position relay R460 completes, at the contacts 461, a series circuit for energizing the windings of the signal relays R885 and R890, this circuit extending from ground in the prepay manual line circuit 280 by way of the control conductor C289 of the telephone line 285, the wiper 317, the control conductor C364 of the trunk 360, the contacts 457, the control conductor C485 of the feeder trunk 480, the contacts 467, the control conductor C471 of the position trunk 470, the contacts 762 of the control key K760, the contacts 792 of the second register key K790, the contacts 797 of the first register key K795, and the windings of R885 and R890 to battery. When this low resistance series circuit is completed for energizing the windings of the signal relays R885 and R890 both of these signal relays operate, thereby to complete, at the contacts 887 and 892, a circuit for illuminating the prepay signal lamp L882, this circuit extending from ground by way of the contacts RA773, 887 and 892 and the prepay signal lamp L882 to battery. The illumination of the prepay signal lamp L882 indicates to the operator at the first A operator position 700

that the call being answered was initiated at a telephone station which is rendered prepay manual service and that the coin deposited in the coin slot of the telephone instrument at the paystation T4 should be either collected or returned to the subscriber thereat.

The operator at the first operator position 700 then answers the call and is advised concerning the extension of the call by the subscriber at the calling paystation T4. The extension of the call from the first A operator position 700 to a called operator position, such, for example, as the first B operator position 694, and the subsequent completion of a direct connection between the paystation T4 and the first B operator position 694 are the same as previously described. Furthermore, the release of the established connection between the calling paystation T4 and the first B operator position 694 is the same as that previously described.

In the present instance, the operator at the first A operator position 700 does not operate the transfer key K765 at her position in order to complete a direct connection between the calling paystation T4 and the first B operator position 694 until after the operator at the first B operator position 694 extends the call to the called subscriber substation in the local exchange 20 and determines whether the call can be completed at this time. In the event the operator at the first B operator position 694 is able to complete the connection to the called subscriber substation at this time, the operator at the first A operator position 700 operates the coin collect key K780 before operating the transfer key K765. On the other hand, in the event the operator at the first B operator position 694 is not able to complete the connection to the called subscriber substation at this time, the subscriber at the calling paystation T4 is so advised by the operator at the first A operator position 700 and the coin return key K785 is operated at the first A operator position 700 before operating the transfer key K765.

When the coin collect key K780 is operated there is completed, at the contacts 783 thereof, an obvious circuit for energizing the winding of the rear split relay R730, thereby to cause the latter relay to operate and complete, at the contacts 732 and 734, an alternative loop circuit between the calling paystation T4 and the coin collect key K780. This loop circuit extends from the line conductor C475 of the position trunk 470 by way of the contacts 734, C747, the contacts 782 of the coin collect key K780, C746 and the contacts 732 to the line conductor C474 of the position trunk 470, the line conductors C475 and C474 of the position trunk 470 being connected to the calling paystation T4 by way of the previously traced circuit. Also, at the contacts 781 of the coin collect key K780, a path is completed for connecting positive 110 volt D. C. potential to the line conductors C286 and C287 of the telephone line 285, this path extending from a source of positive 110 volt D. C. potential by way of the conductor C753, the contacts 781 of the coin collect key K780 to the conductors C746 and C747 and therefrom by way of the contacts 732 and 734 and the line conductors C474 and C475 of the position trunk 470 and the previously traced circuit to the line conductors C286 and C287 of the telephone line 285. The application of positive 110 volt D. C. potential to the line conductors C286 and C287 of the telephone line 285 causes the coin control apparatus at the pay-

station T4 to operate and collect the coin deposited in the coin slot of the telephone instrument thereat.

Subsequently, the coin collect key K780 is returned to its normal position, thereby to interrupt, at the contacts 783, the previously mentioned circuit for energizing the winding of the rear split relay R730, to interrupt, at the contacts 782, the previously traced connection between the line conductors C286 and C287 of the telephone line 285, and to interrupt, at the contacts 781 thereof, the previously traced path for applying positive 110 volt D. C. potential to the line conductors C286 and C287 of the telephone line 285. The rear split relay R730 then restores, thereby to recomplete the loop circuit between the calling paystation T4 and the repeater 701. Subsequently the operator at the first A operator position 700 operates the transfer key K765, thereby to complete the direct loop circuit between the paystation T4 and the line relay R655 in the selector switch 600.

When the coin return key K785 is operated there is completed, at the contacts 788 thereof, an obvious circuit for energizing the winding of the rear split relay R730, thereby to cause the latter relay to operate and complete, at the contacts 732 and 733, an alternative loop circuit between the calling paystation T4 and the coin return key K785. This loop circuit extends from the line conductor C475 of the position trunk 470 by way of the contacts 734, C747, the contacts 787 of the coin return key K785, C746 and the contacts 732 to the line conductor C474 of the position trunk 470, the line conductors C474 and C475 of the position trunk 470 being connected to the calling paystation T4 by way of the previously traced circuit. Also, at the contacts 786 of the coin return key K785, a path is completed for connecting negative 110 volt D. C. potential to the line conductors C286 and C287 of the telephone line 285, this path extending from a source of negative 110 volt D. C. potential by way of the conductor C754, the contacts 786 of the coin return key K785, to the conductors C746 and C747 and therefrom by way of the contacts 732 and 734 and the line conductors C474 and C475 of the position trunk 470 and the previously traced circuit to the line conductors C286 and C287 of the telephone line 285. The application of negative 110 volt D. C. potential to the line conductors C286 and C287 of the telephone line 285 causes the coin control apparatus at the paystation T4 to operate and return the coin deposited in the coin slot of the telephone instrument thereat.

Subsequently, the coin return key K785 is returned to its normal position, thereby to interrupt, at the contacts 788, the previously mentioned circuit for energizing the winding of the rear split relay R730, to interrupt, at the contacts 787, the previously traced connection between the line conductors C286 and C287 of the telephone line 285, and to interrupt, at the contacts 786 thereof, the previously traced path for applying negative 110 volt D. C. potential to the line conductors C286 and C287 of the telephone line 285. The rear split relay R730 then restores, thereby to recomplete the loop circuit between the calling paystation T4 and the repeater 701. Subsequently the operator at the first A operator position 700 operates the transfer key K765, thereby to cause the link 100 illustrated to be released, assuming that the subscriber at the calling paystation T4 has replaced

the receiver of the telephone instrument thereat upon its switchhook at this time.

Call and recall storage

In the previous explanation of the operation of the system it was assumed that the A operator position distributor 830 had previously selected an idle A operator position when the calls were initiated at the subscriber substations T1, T2, and T3 and at the paystation T4, and when the recall was initiated at the first B operator position 694. However, it may occur that all of the A operator positions are busy when one or more calls are initiated at the subscriber substations or paystations, or when one or more recalls are initiated at the various called operator positions. More particularly, by way of review, it is noted in connection with the operation of the switching units in the various groups of switching units and the operation of the A operator position distributor 830 that when a call or recall is routed to the first A operator position 700 to be answered, a path is completed in one of the switching units in the first group of switching units for applying ground potential to the control conductor C883 in the distributor trunk 880, thereby to complete the previously traced circuit for energizing the left-hand winding of the position relay R860 in order to cause operation thereof and the consequent selection by the A operator position distributor 830 of the second A operator position. Also, when the first A operator position 700 is busy, a connection is completed thereat between the control conductors C881 and C883 in the distributor trunk 880, thereby to prevent the A operator position distributor from selecting the first A operator position 700 while others of the A operator positions are idle. Similarly, when a call or recall is routed to the second A operator position 505 to be answered, a path is completed in one of the switching units in the second group of switching units for applying ground potential to the control conductor C887 in the distributor trunk 880, thereby to complete the previously traced circuit for energizing the left-hand winding of the position relay R870 in order to cause operation thereof and the consequent selection by the A operator position distributor 830 of the last A operator position L505. Also, when the second A operator position 505 is busy, a connection is completed thereat between the control conductors C881 and C887 in the distributor trunk 880, thereby to prevent the A operator position distributor 830 from selecting the second A operator position 505 while others of the A operator positions are idle. Finally, when a call or recall is routed to the last A operator position L505 to be answered a path is completed in one of the switching units in the last group of switching units for applying ground potential to the control conductor C885 in the distributor trunk 880, thereby to complete the previously traced circuit for energizing the left-hand winding of the position relay R850 in order to cause operation thereof and the consequent selection by the A operator position distributor 830 of the first A operator position 700. Also, when the last A operator position is busy, a connection is completed thereat between the control conductors C881 and C885 in the distributor trunk 880, thereby to prevent the A operator position distributor from selecting the last A operator position L505 while others of the A operator positions are idle. In view of the foregoing explanation of the mode of operation of the A

operator position distributor 830, it will be understood that the various A operator positions are selected thereby in a predetermined order as long as one of the A operator positions is idle and that the operation thereof is controlled, as each A operator position becomes idle, to prevent it from selecting the busy A operator position as long as there is an idle A operator position.

When all of the A operator positions become busy a chain circuit is completed for energizing the winding of the busy relay R830 in the A operator position distributor 830, this circuit extending from ground in one of the switching units in the last group of switching units by way of the conductor C892, a connection in one of the switching units in the last group of switching units between the conductors C892 and C891, a connection between the conductors C891 and C890 in one of the switching units in the second group of switching units, a connection between the conductors C890 and C882 in one of the switching units in the first group of switching units and the winding of R830 to battery. When thus energized, the busy relay R830 operates to interrupt, at the contacts 831, the previously mentioned path for applying ground potential to the conductor C881 in the distributor trunk 880. When ground potential is removed from the control conductor C881 in the distributor trunk 880 the apparatus at each of the A operator positions, which is normally effective when the associated A operator position is busy for rendering the A operator position distributor 830 ineffective to select the associated A operator position, is rendered ineffective, whereby, when all of the A operator positions are busy, the A operator position distributor 830 becomes effective to again select in a predetermined order each of the busy A operator positions.

Assuming that a call is initiated on the first link 100 in the first group of links at this time and that the A operator position distributor 830 has previously selected the first group of switching units and the corresponding busy first A operator position 700, the presence of the call on the first link 100 in the first group of links causes operation of the first switching unit 400 in the first group of switching units, whereby the feeder relay R450, the start relay R430 and the sequence switch 410 operate in the manner previously explained. At this time the rotary magnet M419 operates intermittently, thereby to drive the wipers noted of the sequence switch 410 step by step in the clockwise direction until the wiper 415 engages the seventh contact in the associated contact bank 416 of the sequence switch 410, whereupon a circuit is completed for energizing in series the winding of the stop relay R440 and the winding of the first storage relay 1M in the first call storage unit 800, this circuit extending from ground by way of the contacts 435, the winding of R440, the wiper 415 and engaged seventh contact in the associated contact bank 416 of the sequence switch 410, the marking conductor C877 in the marking trunk 870, the contacts 821 and the winding of 1M to battery. When this series circuit is completed the stop relay R440 operates, thereby to arrest further operation of the rotary magnet M419 of the sequence switch 410 at this time as previously explained, and the first marking relay 1M operates shortly thereafter, this relay being of the slow-to-operate type, thereby to complete, at the contacts 1M2, the previously mentioned holding circuit for energizing the lower winding of the con-

trol relay R810, the control relay R810 and the release relay R820 being operated at this time due to the operated condition of the start relay R710 at the busy first A operator position 700. Also, 5 the first marking relay 1M completes, at the contacts 1M3, an obvious circuit for illuminating the storage signal lamp L801, the illumination of the storage signal lamp L801 being effective to indicate to the operator at the first A operator position 700 that a call is stored in the first position or setting of the first call storage unit 800. Finally, the first marking relay 1M prepares, 10 at the contacts 1M1, a circuit traced hereinafter for energizing the second marking relay 2M by way of the marking conductor C876 in the marking trunk 870. Upon operating, the start relay R430 completes, at the contacts 433, the previously traced path for applying ground potential to the control conductor C883 in the distributor trunk 880, thereby to cause the A operator position distributor 830 to operate and select the second busy A operator position 505 at this time.

In view of the above description of the mode 25 of operation of the A operator position distributor 830, it will be understood that this distributor operates at this time to select in a predetermined order each of the busy A operator positions, thereby to cause one call or recall to be 30 stored in the call storage units respectively associated with the A operator positions. After one call or recall has been stored in each of the call storage units associated with the busy A operator positions the A operator position distributor 830 35 operates to reselect in a predetermined order the busy A operator positions, whereby a second call or recall is stored in the call storage units individually associated with the A operator positions.

Accordingly, it will be understood that the A 40 operator position distributor 830 operates, when all of the A operator positions are busy, to cause successive calls and recalls to be stored in the call storage units respectively associated with the A operator positions in a predetermined order, whereby as many as six calls or recalls are 45 ultimately stored in each of the call storage units. When six calls have been stored in each of the call storage units the A operator position distributor 830 operates to cause successive calls to be conserved in a predetermined order in the call storage units associated with the A operator positions, whereby a number of calls may be 50 conserved in each of the call storage units when the storage capacity of each call storage unit is exhausted.

In view of the foregoing description of the mode of operation of the A operator position distributor 830, it will be understood that the first call or recall routed to the first A operator position 700, when the first A operator position 60 700 is busy, is stored in the first position or setting of the first call storage unit 800, thereby to cause operation of the first storage relay 1M. Similarly, the second, third, fourth, fifth and sixth calls or recalls routed to the first A operator position 700, while this position is busy, will be stored respectively in the second, third, fourth, fifth and sixth storage settings of the first call storage unit 800, thereby respectively to cause operations of the second, third, fourth, fifth and sixth storage relays 2M, 3M, 4M, 5M and 6M, respectively. The operated storage relays 1M to 6M, inclusive, complete obvious circuits for illuminating the call storage lamps L801 to L806, inclusive, thereby to indicate to the operator at

the busy first A operator position 700 that six calls or recalls are stored in the first call storage unit 800. Upon operating, the sixth call storage relay 6M completes, at the contacts 6M1, an obvious path for applying battery potential by way of the resistor 870' to the marking conductor C871 in the marking trunk 870, thereby to prepare the first call storage unit 800 to conserve an unlimited number of calls or recalls. Accordingly, the first call storage unit 800 comprises 10 a call storer having a limited call storage capacity of six calls and a conservator of unlimited conservation capacity. At this time, when additional calls or recalls are routed to the busy first A operator position 700, they are conserved in 15 the first call storage unit 800. More particularly, at this time, when one of the wipers of one of the sequence switches in the first group of sequence switches engages the first contact in the associated contact bank, a circuit is completed for energizing the stop relay of the switching unit by way of battery at the resistor 870'.

In view of the foregoing description of the mode of operation of the A operator position distributor 830 and the call storage units individually associated with the A operator positions, it will be understood that all incoming calls and recalls are routed in a predetermined order to idle ones of the A operator positions when one or more of the A operator positions are idle. 25 When all of the A operator positions are busy, incoming calls and recalls initiated are stored in order in the call storage units individually associated with the A operator positions until six calls are stored in each call storage unit; and 30 when all of the storage positions in all of the call storage units are occupied, subsequent calls and recalls are conserved in a predetermined order in the call storage units associated with the A operator positions until there are storage facilities in the call storage units. 40

Continuing now with the operation of one of the call storage units, for example, the first call storage unit 800 individually associated with the first A operator position 700, when the first A operator position becomes idle the start relay R770 restores, thereby to interrupt, at the contacts RA772, the previously traced series circuit for energizing the upper winding of the control relay R810 and the winding of the release relay R820. The release relay R820 restores; however, the control relay R810 does not restore due to the completed holding circuit for energizing the lower winding thereof. Upon restoring, the release relay R820 interrupts, at the contacts 821, the previously traced circuit for energizing in series the winding of the first call storage relay 1M and the winding of the stop relay in one of the switching units in the first group of switching units, thereby to cause the first call storage relay 1M to restore and to cause the sequence switch occupying the first storage position of the first call storage unit 800 to be reoperated, whereupon the last-mentioned sequence switch operates to cause the call or recall on the link associated therewith to be routed to the first A operator position 700 to be answered, thereby again to render the first A operator position 700 busy. 55

When the first call storage position in the first call storage unit 800 becomes idle the first storage relay 1M restores, thereby to cause successive restoration of the second, third, fourth, fifth and sixth storage relays 2M, 3M, 4M, 5M and 6M, respectively. When the first storage relay 1M restores, further operation of the sequence switch 60

associated with the second storage position of the call storage unit 800 is initiated. Accordingly, restorations of the storage relays 1M, 2M, 3M, 4M and 5M cause the sequence switches respectively associated with the second, third, fourth, fifth and sixth storage positions of the call storage unit 800 to be reoperated. More particularly, the sequence switch associated with the second storage position of the call storage unit 800 is operated one step, or to the first storage position of the call storage unit 800, and the first storage relay 1M is reoperated, whereupon operation of this sequence switch is arrested, thus causing the call or recall on the link associated with the sequence switch associated with the second storage position of the call storage unit 800 to be advanced to a position corresponding to the first storage position of the call storage unit 800. Similarly, each of the sequence switches is advanced one position, thereby to cause the calls on the associated links stored in the second, third, fourth, fifth and sixth positions of the call storage unit 800 to be advanced to storage in the first, second, third, fourth and fifth storage positions of the call storage unit 800. In view of the above explanation of the mode of operation of the call storage unit 800, it will be understood that the calls stored in the various storage positions thereof are sequentially advanced toward the first storage position thereof and then routed therefrom to the first A operator position 700 to be answered.

It is noted that when the sequence switch associated with the sixth storage position of the call storage unit 800 is advanced to the fifth storage position thereof the sixth storage relay 6M in the call storage unit 800 restores, thereby to interrupt, at the contacts 6M1, the previously traced path for applying battery potential by way of the resistor 870' to the marking conductor C871 in the marking trunk 870, thus causing reoperation of each of the sequence switches having one wiper engaging the first contact in the associated contact bank. More particularly, these sequence switches reoperate and the wiper of one of them first engages the second contact in the associated contact bank, thereby to cause the call or recall on the associated link previously conserved in the call storage unit 800 to be stored in the sixth storage position thereof. When the new call or recall is stored in the sixth storage position of the call storage unit 800 the sixth storage relay 6M reoperates, thereby to recomplete, at the contacts 6M1, the previously traced path for applying battery potential by way of the resistor 870' to the marking conductor C871 in the marking trunk 870. Accordingly, the remainder of the last-mentioned sequence switches reoperate, thereby to cause one wiper of each of these switches to engage the first contact in the associated contact bank, whereupon the calls or recalls on the links associated with the last-mentioned sequence switches are again placed in conservation in the first call storage unit 800. 65

In view of the foregoing explanation of the mode of operation of the first call storage unit 800 in order to release calls and recalls from conservation and to place these calls and recalls in storage, it will be understood that the calls and recalls in conservation are released from storage indiscriminately.

In view of the foregoing explanation of the mode of operation of the first call storage unit 800 individually associated with the first A operator position 700, it will be understood that all

calls and recalls conserved or stored in a given call storage unit must be answered by the operator at the individually associated operator position. Furthermore, all incoming calls and recalls conserved in a given call storage unit are later transferred to the call storage unit to be stored when the storage capacity of the storage unit is replenished, while the calls stored in the storage unit are released to the associated operator position to be answered in the same order as stored in the storage unit. Hence, each call storage unit comprises not only a call conserving and a call storer but also a call storage distributor.

Finally, it is noted that when any one of the A operator positions becomes idle the previously traced chain circuit for energizing the winding of the busy relay R830 is interrupted, thereby to cause the latter relay to restore and recomplete, at the contacts 831, the previously traced circuits for rendering the apparatus at the various busy A operator positions effective to prevent the A operator position distributor 830 from selecting the busy A operator positions to have either calls or recalls conserved or stored in the associated call storage units.

Conclusions

From the foregoing it is apparent that a telephone system is provided which comprises an exchange including a number of operator positions and an improved distributor arrangement for routing, in a predetermined order, incoming calls and recalls to the exchange to the operator positions to be answered. Also the exchange embodies an improved call storage arrangement for storing, in a predetermined order, incoming calls and recalls to the exchange when all of the operator positions are busy and for subsequently releasing the stored calls and recalls in the same predetermined order to the operator positions to be answered as the operator positions become idle.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an assigned one of said storage units to be stored, means for routing a call upon said one subscriber line stored in said assigned storage unit to the associated one of said A operator positions to be answered, means for routing a call from said one A operator position to said B operator position, means for establishing a connection between said one subscriber line and said B operator position independent of said one A operator position, thereby to route a call from said one subscriber line to said B operator position, means for routing a recall by an operator at said B operator position upon said established connection to an assigned one of said storage units to be stored, and means for routing a recall upon said established connection stored in said assigned storage

unit to the associated one of said A operator positions to be answered.

2. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an idle one of said A operator positions to be answered when one of said A operator positions is idle, means for routing a call upon said one subscriber line to an assigned one of said storage units to be stored when all of said A operator positions are busy, means for routing a call upon said one subscriber line stored in said assigned storage unit to the associated one of said A operator positions to be answered when the associated A operator position becomes idle, means for routing a call from said one A operator position to said B operator position, means for establishing a connection between said one subscriber line and said B operator position independent of said one A operator position, thereby to route a call from said one subscriber line to said B operator position, means for routing a recall by an operator at said B operator position upon said established connection to an idle one of said A operator positions to be answered when one of said A operator positions is idle, means for routing a recall upon said established connection to an assigned one of said storage units to be stored when all of said A operator positions are busy, and means for routing a recall upon said established connection stored in said assigned storage unit to the associated one of said A operator positions to be answered when the associated A operator position becomes idle.

3. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an assigned one of said storage units to be stored, means for routing a call upon said one subscriber line stored in said assigned storage unit to the associated one of said A operator positions to be answered, means for routing a call from said one A operator position to said B operator position, means for establishing a connection between said one subscriber line and said B operator position independent of said one A operator position, thereby to route a call from said one subscriber line to said B operator position, and means for routing a recall by an operator at said B operator position upon said established connection to an idle one of said A operator positions to be answered.

4. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an idle one of said A operator positions to be answered when one of said A operator positions is idle, means for routing a call upon said one subscriber line to an assigned one of said storage units to be stored when all of said A operator positions are busy, means for routing a call upon said one subscriber line stored in said assigned storage unit to the associated one of said A operator positions to be answered.

erator positions to be answered when the associated A operator position becomes idle, means for routing a call from said one A operator position to said B operator position, means for establishing a connection between said one subscriber line and said B operator position independent of said one A operator position, thereby to route a call from said one subscriber line to said B operator position, and means for positively routing a recall by an operator at said B operator position upon said established connection to an idle one of said A operator positions to be answered.

5. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an idle one of said A operator positions to be answered, means for routing a call from said one A operator position to said B operator position, means for establishing a connection between said one subscriber line and said B operator position independent of said one A operator position, thereby to route a call from said one subscriber line to said B operator position, means for routing a recall by an operator at said B operator position upon said established connection to an assigned one of said storage units to be stored, and means for routing a recall upon said established connection stored in said assigned storage unit to the associated one of said A operator positions to be answered.

6. In a telephone system, a plurality of subscriber lines, a plurality of A operator positions, a B operator position, a plurality of storage units individually associated with said A operator positions, means for assigning said storage units in a predetermined order, means for routing a call upon any one of said subscriber lines to an idle one of said A operator positions to be answered, means for routing a call from said one A operator position to said B operator position, means for establishing a connection between said one subscriber line and said B operator position independent of said one A operator position, thereby to route a call from said one subscriber line to said B operator position, means for routing a recall by an operator at said B operator position upon said established connection to an idle one of said A operator positions to be answered when one of said A operator positions is idle, means for routing a recall upon said established connection to an assigned one of said storage units when all of said A operator positions are busy, and means for routing a recall upon said established connection stored in said assigned storage unit to the associated one of said A operator positions to be answered when the associated A operator position becomes idle.

7. In a telephone system, a plurality of lines, a link including an answer switch having access to said lines and a call switch, means controlled by the presence of a call on any one of said lines for causing the answer switch of said link to seize said one line, thereby to extend the call to said link, a plurality of operator positions, a plurality of storage units individually associated with said operator positions, means for routing a call on said link to an idle one of said operator positions to be answered when one of said operator positions is idle, means for assigning said storage units in a predetermined order

order when all of said operator positions are busy, means for routing a call on said link to an assigned one of said storage units to be stored, means for routing a call on said link stored in said assigned storage unit to the associated operator position to be answered when the associated operator position becomes idle, and means under the control of an operator at any one of said operator positions to which the call on said link is routed for governing the operation of the call switch of said link, thereby to extend the call from said one operator position.

8. In a telephone system, a plurality of lines, a plurality of links each including an answer switch having access to said lines and a call switch, means controlled by the presence of calls on said lines for assigning said links for use in a predetermined order and for causing the answer switches of said assigned links to seize said lines having calls thereon, thereby to extend the calls on said lines to said assigned links, a plurality of operator positions, a plurality of storage units individually associated with said operator positions, means for routing the calls on said assigned links to idle ones of said operator positions to be answered when said operator positions are idle, means for assigning said storage units in a predetermined order when all of said operator positions are busy, means for routing the calls on said assigned links to assigned ones of said storage units to be stored, means for routing the calls on said assigned links stored in said assigned storage units to the associated ones of said operator positions to be answered when the associated operator positions become idle, and means under the control of an operator at any one of said operator positions to which the call on any one of said assigned links is routed for governing the operation of the call switch of said one assigned link, thereby to extend the call from said one operator position.

9. In a telephone system, a plurality of lines, a link including a first branch provided with an answer switch having access to said lines and a second branch provided with a call switch, means controlled by the presence of a call on any one of said lines for causing the answer switch of said link to seize said one line, thereby to extend the call to said link, a plurality of operator positions each including telephone apparatus, a plurality of storage units individually associated with said operator positions, means for routing a call on said link to an idle one of said operator positions to be answered when one of said operator positions is idle, means for assigning said storage units in a predetermined order when all of said operator positions are busy, means for routing a call on said link to an assigned one of said storage units to be stored, means for routing a call on said link stored in said assigned storage unit to the associated operator position to be answered when the associated operator position becomes idle, means under the control of an operator at any one of said operator positions to which the call on said link is routed for governing the operation of the call switch of said link, thereby to extend the call from said one operator position, means at any one of said operator positions for completing a three-way communication connection including the telephone apparatus thereat and the first and the second branches of said link, and means under the control of an operator at any one of said operator positions for completing a communication connection between

the first and the second branches of said link independent of said one operator position.

10. In a telephone system, a plurality of lines, a plurality of links each including a first branch provided with an answer switch having access to said lines and a second branch provided with a call switch, means controlled by the presence of calls on said lines for assigning said links for use in a predetermined order and for causing the answer switches of said assigned links to seize said lines having calls thereon, thereby to extend the calls on said lines to said assigned links, a plurality of operator positions each including telephone apparatus, a plurality of storage units individually associated with said operator positions, means for routing the calls on said assigned links to idle ones of said operator positions to be answered when said operator positions are idle, means for assigning said storage units in a predetermined order when all of said operator positions are busy, means for routing the calls on said assigned links to assigned ones of said storage units to be stored, means for routing the calls on said assigned links stored in said assigned storage units to the associated ones of said operator positions to be answered when the associated operator positions become idle, means under the control of an operator at any one of said operator positions to which the call on an assigned one of said links is routed for governing the operation of the call switch of said one assigned link, thereby to extend the call from said one operator position, means at any one of said operator positions for completing a three-way communication connection including the telephone apparatus thereat and the first and the second branches of an assigned one of said links, and means under the control of an operator at any one of said operator positions for completing a communication connection between the first and the second branches of an assigned one of said links independent of said one operator position.

11. In a telephone system, a calling line, a called line, a link including an answer switch having access to said calling line and a call switch having access to said called line, means for causing the answer switch of said link to seize said calling line, thereby to extend the call to said link, a plurality of operator positions, a plurality of storage units individually associated with said operator positions, means for routing a call on said link to an idle one of said operator positions to be answered when one of said operator positions is idle, means for assigning said storage units in a predetermined order when all of said operator positions are busy, means for routing a call on said link to an assigned one of said storage units to be stored, means for routing a call on said link stored in said assigned storage unit to the associated operator position to be answered when the associated operator position becomes idle, call means at each one of said operator positions operative to cause the call switch of said link to seize said called line, thereby to complete a connection between said calling line and said called line including said one operator position, transfer means at each one of said operator positions operative to cause the completion of a connection between said calling line and said called line excluding said one operator position, means under the joint control of said calling line and an operator at any one of said operator positions to which a call on said link is routed for releasing the connection prior to the opera-

tion of the call means at said one operator position, and means under the joint control of said calling line and said called line for releasing the connection subsequent to the operation of the transfer means at the one of said operator positions to which the call on said link was routed.

12. In a telephone system, a plurality of calling lines, a plurality of called lines, a plurality of links each including an answer switch having access to said calling lines and a call switch having access to said called lines, means for assigning said links in a predetermined order and for causing the answer switches of said assigned links to seize said calling lines, thereby to extend the calls to said assigned links, a plurality of operator positions, a plurality of storage units individually associated with said operator positions, means for routing the calls on said assigned links to idle ones of said operator positions to be answered when said operator positions are idle, means for assigning said storage units in a predetermined order when all of said operator positions are busy, means for routing the calls on said assigned links to assigned ones of said storage units to be stored, means for routing the calls on said assigned links stored in said assigned storage units to the associated ones of said operator positions to be answered when the associated operator positions become idle, calling means at said operator positions operative to cause the call switches of said assigned links to seize said called lines, thereby to complete connections between said calling lines and said called lines including said operator positions, transfer means at said operator positions operative to cause the completion of connections between said calling lines and said called lines excluding said operator positions, means under the joint control of any one of said calling lines and an operator at any one of said operator positions to which a call on the corresponding one of said assigned links is routed for releasing the connection prior to the operation of the calling means at said one operator position, and means under the joint control of any one of said calling lines and the corresponding one of said called lines for releasing the connection subsequent to the operation of the transfer means at the one of said operator positions to which the call on the corresponding one of said assigned links was routed.

13. In a telephone system, a plurality of lines, means for establishing a connection between two of said lines, thereby to route a call from one of said lines to the other of said lines, a plurality of operator positions, a plurality of storage units individually associated with said operator positions, means for assigning said storage units in a predetermined order, means for routing a recall upon said established connection to an assigned one of said storage units to be stored, and means for routing a recall upon said established connection stored in said assigned storage unit to the associated operator position to be answered.

14. In a telephone system, a plurality of lines, means for establishing a connection between two of said lines, thereby to route a call from one of said lines to the other of said lines, a plurality of operator positions, a plurality of storage units individually associated with said operator positions, means for routing a recall upon said established connection to an idle one of said operator positions to be answered when one of said operator positions is idle, means for assigning said storage units in a predetermined order when all of said operator positions are busy, means for

routing a recall upon said established connection to an assigned one of said storage units to be stored, and means for routing a recall upon said established connection stored in said assigned storage unit to the associated operator position to be answered when the associated operator position becomes idle.

15. In a telephone system, a plurality of lines, a plurality of operator positions, a plurality of storage units individually associated with said operator positions, means for assigning said storage units in a predetermined order, means for routing a call upon any one of said lines to an assigned one of said storage units to be stored, means for routing a call upon said one line stored in said assigned storage unit to the associated operator position to be answered, means for routing a call from said one operator position to another of said lines, means for establishing a connection between said one line and said other line independent of said one operator position, thereby to route a call from said one line to said other line, means for routing a recall upon said established connection to an assigned one of said storage units to be stored, and means for routing a recall upon said established connection stored in said assigned storage unit to the associated operator position to be answered.

16. In a telephone system, a plurality of lines, a plurality of operator positions, a plurality of storage units individually associated with said operator positions, means for assigning said storage units in a predetermined order, means for routing a call upon any one of said lines to an idle one of said operator positions to be answered when one of said operator positions is idle, means for routing a call upon said one line to an assigned one of said storage units to be stored when all of said operator positions are busy, means for routing a call upon said one line stored in said assigned storage unit to the associated operator position to be answered when the associated operator position becomes idle, means for routing a call from said one operator position to another of said lines, means for establishing a connection between said one line and said other line independent of said one operator position, thereby to route a call from said one line to said other line, means for routing a recall upon said established connection to an idle one of said operator positions to be answered when one of said operator positions is idle, means for routing a recall upon said established connection to an assigned one of said storage units to be stored when all of said operator positions are busy, and means for routing a recall upon said established connection stored in said assigned storage unit to the associated operator position to be answered when the associated operator position becomes idle.

17. In a telephone system, a plurality of operator positions, a plurality of trunks, a plurality of storage units individually associated with said operator positions, a plurality of conservators individually associated with said storage units, each of said storage units having a limited storage capacity, each of said conservators having an unlimited conservation capacity, means for assigning said storage units in a predetermined order when all of said operator positions are busy and for assigning said conservators in a predetermined order when the storage capacities of said storage units are exhausted, means for routing calls on said trunks to said operator positions to be answered when said operator posi-

tions are idle, means for routing calls on said trunks to assigned ones of said storage units to be stored, means for routing calls on said trunks stored in said assigned storage units to the associated ones of said operator positions to be answered when the associated operator positions become idle, means for routing calls on said

5 trunks to assigned ones of said conservators to be conserved, and means for routing calls on said trunks conserved in said assigned conservators to the associated ones of said storage units to be stored when the storage capacities of the associated storage units are replenished.

18. In a telephone system, a plurality of operator positions, a plurality of storage units individually associated with said operator positions, a plurality of trunks, switching apparatus having access to said operator positions and to said storage units, means for causing said switching apparatus to route calls on said trunks directly to said operator positions to be answered independently of said storage units when said operator positions are idle, means for causing said switching apparatus to route calls on said trunks directly to said storage units in a predetermined order to be stored only when all of said operator positions are busy, means for causing said switching apparatus to route any calls on said trunks stored in said storage units to the associated ones of said operator positions to be answered as the associated operator positions become idle, a plurality of storage distributors individually associated with storage units, and means including any given storage distributor for controlling the order in which calls on said trunks stored in the associated storage unit are routed by said switching apparatus to the associated operator position.

19. In a telephone system, a plurality of operator positions, a plurality of storage units individually associated with said operator positions, a plurality of trunks, switching apparatus having access to said operator positions and to said storage units, means for causing said switching apparatus to route calls on said trunks directly to selected ones of said operator positions to be answered independently of said storage units, means including a position distributor for selecting in a predetermined order said operator positions, means for causing said switching apparatus to route calls on said trunks directly to said storage units in a predetermined order to be stored only when there is no selected operator position, and means for causing said switching apparatus to route any calls on said trunks stored in said storage units to the associated ones of said operator positions to be answered independently of said position distributor.

20. In a telephone system, a plurality of operator positions, a plurality of storage units individually associated with said operator positions, a plurality of trunks, switching apparatus having access to said operator positions and to said storage units, a position distributor, means for causing said position distributor to select an idle operator position, means controlled when a selected operator position is rendered busy for causing said position distributor to select another idle operator position, means controlled when a call is routed to an operator position to be answered for rendering busy the operator position, means controlled after a call routed to an operator position is answered thereat for rendering idle the operator position, means for causing said switching apparatus to route calls on said trunks directly to selected ones of said

operator positions independently of said storage units, means for causing said switching apparatus to route calls on said trunks directly to said storage units in a predetermined order to be stored only when there is no selected operator position, and means for causing said switching apparatus to route any calls on said trunks stored in said storage units to the associated ones of said operator positions to be answered as the associated operator positions become idle independently of said position distributor.

21. In a telephone system, a plurality of operator positions, a plurality of storage units individually associated with said operator positions, a plurality of trunks, switching apparatus having access to said operator positions and to said storage units, a position distributor operative automatically to test for an idle operator position, means for arresting operation of said position distributor when an idle operator position is tested and for causing said position distributor to select the operator position tested idle, means controlled when a selected operator position is rendered busy for initiating further operation of said position distributor, means controlled when a call is routed to an operator position to be answered for rendering busy the operator position, means controlled after a call routed to an operator position is answered thereby for rendering idle the operator position, means for causing said switching apparatus to route calls on said trunks directly to a selected one of said operator positions independently of said storage units, means for causing said switching apparatus to route calls on said trunks directly to said storage units in a predetermined order to be stored only when there is no selected operator position, and means for causing said switching apparatus to route any calls on said trunks stored in said storage units to the associated ones of said operator positions to be answered as the associated operator positions become idle independently of said position distributor.

22. In a telephone system, a link, a plurality of operator positions, a plurality of relays individually associated with said operator positions and commonly associated with said link, each of said relays being operative to connect said link to the associated operator position, means including a position distributor for preparing said relays in a predetermined order, means controlled by the presence of a call on said link for causing operation of a prepared one of said relays, thereby to extend the call on said link to the operator position associated with said one relay to be answered, and means controlled by the operation of said one relay for preventing operation of the other of said relays.

23. In a telephone system, a link, a plurality of operator positions, a plurality of relays individually associated with said operator positions and commonly associated with said link, each of said relays being operative to connect said link to the associated operator position, a position distributor normally operative to prepare said relays in a predetermined order, means operative under the control of an operator at any one of said operator positions for preventing said position distributor from preparing the relay associated with said one operator position, means controlled by the presence of a call on said link for causing operation of a prepared one of said relays, thereby to extend the call on said link

to the operator position associated with said one relay to be answered, and means controlled by the operation of said one relay for preventing operation of the other of said relays.

5 24. In a telephone system, a first group of lines, a second group of lines, a link including an answer switch having access to said first group of lines and a call switch having access to said second group of lines, means for causing the answer switch of said link to seize a calling line in said first group of lines, thereby to extend the call on said calling line to said link, a plurality of operator positions, a plurality of relays individually associated with said operator positions and commonly associated with said link, each of said relays being operative to connect said link to the associated operator position, means including a position distributor for preparing said relays in a predetermined order, means controlled by the presence of a call on said link for causing operation of a prepared one of said relays, thereby to extend the call on said link to the operator position associated with said one relay to be answered, means controlled by the operation of said one relay for preventing operation of the other of said relays, and means under the control of an operator at said last-mentioned operator position for causing the call switch of said link to seize a called line in said second group of lines, thereby to extend the call on said link to said called line.

20 25. In a telephone system, a first group of lines, a second group of lines, a plurality of links each including an answer switch having access to said first group of lines and a call switch having access to said second group of lines, means including a link distributor for assigning said link in a predetermined order and for causing the answer switch of an assigned link to seize a calling line in said first group of lines, thereby to extend the call on said calling line to said assigned link, an operator position, a plurality of relays individually associated with said links and commonly associated with said operator position, 40 each of said relays being operative to connect the associated link to said operator position, means for preparing said relays, means controlled by the presence of a call on an assigned one of said links for causing operation of the prepared associated one of said relays, thereby to extend the call on said assigned link to said operator position to be answered, means controlled by the operation of said one relay for preventing operation of the other of said relays, and means under 50 the control of an operator at said operator position for causing the call switch of said assigned link to seize a called line in said second group of lines, thereby to extend the call on said assigned link to said called line.

60 26. In a telephone system, a plurality of links, a plurality of operator positions, a plurality of relays, said relays being arranged in a plurality of first groups individually associated with said operator positions and in a plurality of second groups individually associated with said links, whereby each relay is included in a particular first group and in a particular second group and is operative to connect the associated link to the associated operator position, means including a position distributor for preparing said first groups of relays in a predetermined order, means controlled by the presence of a call on any one of said links for causing operation of the associated one of said relays in a prepared first group of

relays, thereby to extend the call on said one link to the operator position associated with said one relay to be answered, said one relay being included in a given first group and in a given second group, and means controlled by the operation of said one relay for preventing operation of the other relays in said given first group and the other relays in said given second group.

27. In a telephone system, a plurality of links, a plurality of operator positions, a plurality of relays, said relays being arranged in a plurality of first groups individually associated with said operator positions and in a plurality of second groups individually associated with said links, whereby each relay is included in a particular first group and in a particular second group and is operative to connect the associated link to the associated operator position, a position distributor normally operative to prepare said first groups of relays in a predetermined order, means operative under the control of an operator at any one of said operator positions for preventing said position distributor from preparing the first group of relays associated with said one operator position, means controlled by the presence of a call on any one of said links for causing operation of the associated one of said relays in a prepared first group of relays, thereby to extend the call on said one link to the operator position associated with said one relay to be answered, said one relay being included in a given first group and in a given second group, and means controlled by the operation of said one relay for preventing operation of the other relays in said given first group and the other relays in said given second group.

28. In a telephone system, a plurality of links, a plurality of operator positions, a plurality of relays, said relays being arranged in a plurality of first groups individually associated with said operator positions and in a plurality of second groups individually associated with said links, whereby each relay is included in a particular first group and in a particular second group and is operative to connect the associated link to the associated operator position, means including a position distributor for preparing any one of said first groups of relays associated with an idle one of said operator positions, means controlled by the presence of a call on any one of said links for causing operation of the associated one of said relays in a prepared first group of relays, thereby to extend the call on said one link to the operator position associated with said one relay to be answered, said one relay being included in a given first group and in a given second group, and means controlled by the operation of said one relay for preventing operation of the other relays in said given first group and the other relays in said given second group.

29. In a telephone system, a plurality of links, a plurality of operator positions, a plurality of relays, said relays being arranged in a plurality of first groups individually associated with said operator positions and in a plurality of second groups individually associated with said links, whereby each relay is included in a particular first group and in a particular second group and is operative to connect the associated link to the associated operator position, a position distributor, means for causing said position distributor to prepare one of said first groups of relays associated with an idle one of said operator positions, means controlled by the presence of a call on any one of said links for causing operation

of the prepared associated one of said relays in said one first group of relays, thereby to extend the call on said one link to said one operator position to be answered, means controlled when the call on said one link is extended to said one operator position for rendering busy said one operator position, means controlled after the call on said one link is answered at said one operator position for rendering idle said one operator position, means controlled by the operation of said one relay for preventing operation of the other relays in said one first group and the other relays in the particular second group including said one relay, and additional means controlled by the operation of said one relay for causing said position distributor to prepare another of said first groups of relays associated with an idle one of said operator positions.

30. In a telephone system, a first group of lines, a second group of lines, a plurality of links each including an answer switch having access to said first group of lines and a call switch having access to said second group of lines, means including a link distributor for assigning said links in a predetermined order and for causing the answer switch of an assigned link to seize a calling line in said first group of lines, thereby to extend the call on said calling line to said assigned link, a plurality of operator positions, a plurality of relays, said relays being arranged in a plurality of first groups individually associated with said operator positions and in a plurality of second groups individually associated with said links, whereby each relay is included in a particular first group and in a particular second group and is operative to connect the associated link to the associated operator position, means including a position distributor for preparing said first groups of relays in a predetermined order, means controlled by the presence of a call on an assigned one of said links for causing operation of the associated one of said relays in a prepared first group of relays, thereby to extend the call on said assigned link to the operator position associated with said one relay to be answered, said one relay being included in a given first group and in a given second group, and means controlled by the operation of said one relay for preventing operation of the other relays in said given first group and the other relays in said given second group, and means under the control of an operator at said last-mentioned operator position for causing the call switch of said assigned link to seize a called line in said second group of lines, thereby to extend the call on said assigned link to said called line.

31. In a telephone system, a plurality of groups of links, a plurality of feeder trunks individually associated with said groups of links, a plurality of automatic switches individually associated with said groups of links, an operator position, a position trunk associated with said operator position, means controlled by the presence of a call on any one of said links in any one of said groups of links for connecting said one link in said one group of links to the associated one of said feeder trunks and for preventing the other links in said one group of links from being connected to said one feeder trunk and for operating the associated one of said switches, and means controlled by the operation of said one switch for connecting said one feeder trunk to said position trunk and for preventing the other of said feeder trunks from being connected to said position trunk, thereby to extend the call on said one link

in said one group of links to said operator position to be answered.

32. In a telephone system, a calling line, a called line, a plurality of groups of links, each of said links including an answer switch having access to said calling line and a call switch having access to said called line, means for assigning said links in said groups of links in a predetermined order and for causing the answer switch of an assigned one of said links in any one of said groups of links to seize said calling line, thereby to extend a call to said one link in said one group of links, a plurality of feeder trunks individually associated with said groups of links, a plurality of automatic switches individually associated with said groups of links, an operator position, a position trunk associated with said operator position, means controlled by the presence of a call on any one of said links in any one of said groups of links for connecting said one link in said one group of links to the associated one of said feeder trunks and for preventing the other links in said one group of links from being connected to said one feeder trunk and for operating the associated one of said switches, means controlled by the operation of said one switch for connecting said one feeder trunk to said position trunk and for preventing the other of said feeder trunks from being connected to said position trunk, thereby to extend the call on said one link in said one group of links to seize said called line, thereby to extend the call on said one link in said one group of links to said called line.

33. In a telephone system, first and second and third groups of lines, first and second groups of links, each link in said first group of links including an answer switch having access to said first group of lines and a call switch having access to said third group of lines, each link in said second group of links including an answer switch having access to said second group of lines and a call switch having access to said third group of lines, means including a first link distributor for assigning said links in said first group of links in a predetermined order and for causing the answer switch of an assigned link in said first group of links to seize a calling line in said first group of lines, means including a second link distributor for assigning said links in said second group of links in a predetermined order and for causing the answer switch of an assigned link in said second group of links to seize a calling line in said second group of lines, any one of said links in any one of said groups of links having a call thereon when the answer switch thereof seizes a calling line, first and second feeder trunks individually associated with said first and second groups of links, first and second automatic switches individually associated with said first and second groups of links, an operator position, a position trunk associated with said operator position, means controlled by the presence of a call on any one of said links in any one of said groups of links for connecting said one link in said one group of links to the associated one of said feeder trunks and for preventing the other links in said one group of links from being connected to said one feeder trunk and for operating the associated one of said switches, means controlled by the operation of said one switch for connecting said one feeder trunk to said position trunk and for

75 preventing the other of said feeder trunks from being connected to said position trunk, thereby to extend the call on said one link in said one group of links to said operator position to be answered, and means controlled by an operator at said operator position for causing the call switch of said one link in said one group of links to seize a called line in said third group of lines, thereby to extend the call on said one link in said one group of links to said called line.

34. In a telephone system, a plurality of groups of links, a plurality of feeder trunks individually associated with said groups of links, a plurality of automatic switches individually associated with said groups of links, an operator position, a position trunk associated with said operator position, a storage unit, means controlled by the presence of a call on any one of said links in any one of said groups of links for connecting said one link in said one group of links to the associated one of said feeder trunks and for preventing the other links in said one group of links from being connected to said one feeder trunk and for operating the associated one of said switches, means controlled by the operation of said one switch for causing the call on said one link in said one group of links to be stored in said storage unit, means for reoperating said one switch, and means controlled by the reoperation of said one switch for causing the call on said one link in said one group of links stored in said storage unit to be released from storage and for connecting said one feeder trunk to said position trunk and for preventing the other of said feeder trunks from being connected to said position trunk, thereby to extend the call on said one link in said one group of links to said operator position to be answered.

35. In a telephone system, a plurality of groups of links, a plurality of feeder trunks individually associated with said groups of links, a plurality of automatic switches individually associated with said groups of links, an operator position, a position trunk associated with said operator position, a storage unit, means controlled by the presence of a call on any one of said links in any one of said groups of links for connecting said one link in said one group of links to the associated one of said feeder trunks and for preventing the other links in said one group of links from being connected to said one feeder trunk and for operating the associated one of said switches, said one switch being operative from a normal position to first and second positions, means controlled when said operator position is busy for causing operation of said one switch from said normal position to said first position, means controlled when said operator position becomes idle for causing operation of said one switch from said first position to said second position, means controlled when said operator position is idle for causing operation of said one switch from said normal position to said second position, means controlled by the operation of said one switch to said first position for causing the call on said one link in said one group of links to be stored in said storage unit, means controlled by the operation of said one switch to said second position for connecting said one feeder trunk to said position trunk and for preventing the other of said feeder trunks from being connected to said position trunk, thereby to extend the call on said one link in said one group of links to said operator position to be answered.

36. In a telephone system, a plurality of groups

of links, a plurality of groups of feeder trunks individually associated with said groups of links, a plurality of groups of automatic switches individually associated with said groups of links, a plurality of operator positions, a plurality of position trunks individually associated with said operator positions, each of said position trunks being associated with corresponding feeder trunks in said groups of feeder trunks, means including a position distributor for selecting corresponding feeder trunks in said groups of feeder trunks and corresponding switches in said groups of switches in a predetermined order, means controlled by the presence of a call on any one of said links in any one of said groups of links for connecting said one link in said one group of links to the selected feeder trunk in the associated one of said groups of feeder trunks and for preventing the other links in said one group of links from being connected to said selected feeder trunk in said one group of feeder trunks and for operating the selected switch in the associated one of said groups of switches, and means controlled by the operation of said selected switch in said one group of switches for connecting said selected feeder trunk in said one group of feeder trunks to the associated one of said position trunks and for preventing the corresponding feeder trunks in said other groups of feeder trunks from being connected to said one position trunk, thereby to extend the call on said one link in said one group of links to the operator position associated with said one position trunk to be answered.

37. In a telephone system, a plurality of telephone lines of different classes, a plurality of line circuits of corresponding classes individually associated with said telephone lines, said line circuits of different classes having different impedance characteristics, an operator position, means

for establishing a connection between any one of said telephone lines and said operator position, means for testing the impedance characteristic of the line circuit associated with a telephone line included in an established connection to said operator position, a plurality of signals associated with said operator position and corresponding to said different classes of telephone lines, and means controlled by said testing means for selectively controlling the operations of said signals, 5 whereby a signal corresponding to a particular class of telephone lines is operated when a connection is completed between any telephone line of said particular class and said operator position. 10 38. In a telephone system, a two-party line, a line circuit associated with said line including first and second registers and a lock-out relay, an operating circuit for said lock-out relay, a holding circuit for said lock-out relay, an operator position, switching apparatus operative to establish a connection between said line and said operator position, means controlled by the presence of a calling condition on said line for operating said switching apparatus, means at said operator position for selectively operating said first and second registers, additional means at said operator position for completing said operating circuit, means controlled by the operation of said lock-out relay for completing said holding circuit and for causing said switching apparatus to restore, means controlled by the operation of said lock-out relay for preventing re-operation of said switching apparatus, and means controlled when the calling condition is removed from said line for interrupting said holding circuit, thereby to cause said lock-out relay to restore.

THOMAS FREDERICK CROCKER.
